UNITED STATES PATENT OFFICE.

ROBERT GREER, OF NEW YORK, N. Y.

TYPE CASTING AND SETTING MACHINE.

Application filed December 20, 1920. Serial No. 432,035.

To all whom it may concern:

Be it known that I, ROBERT GREER, a citizen of the United States, residing at the city of New York, in the county of Kings and State of New York, have invented certain new and useful Improvements in Type Casting and Setting Machines, of which the following is a specification.

This invention relates to type forming, casting and setting machines and is especially designed and improved to meet all requirements of this art.

This is an automatic type forming and setting machine of that general class where-
15 in one character at a time is cast and set in correct relation to form the desired composition. In the said machine, a matrix block containing a complete set of matrices for a font of type, is used in cooperation with ad-
20 justable mold for casting type, and hence it is necessary that certain of the operating parts of the machine, be set, and that cer-
tain other of the parts be adjusted for the proper selection of a matrix and for the cast-
25 ing of a type character in said matrix. The setting and adjustment of the type casting mechanism is controlled in machines of this class, by a perforated strip, which allows an electric circuit to be closed at the proper
30 moment to energize electric magnets for the operation of the character selecting and casting mechanism in cooperation with ac-
tuating means such as cams of correct de-
sign.

35 For the purpose of brevity, in what follows, I will use the term "point size" to indicate the thickness of the type body from top to bottom as viewed on a printed page, for the reason that the above described di-
40 mension of type is usually given in mul-
tiple of points, as for instance, 6 point type,
12 point type and the like; and I will use the term "face size" to indicate the width of the type body of type of any given point
45 size from side to side.

In machines of this type a number of different parts must each be set in a pre-determined position at the proper time to effect the selection of the desired matrix, 50 or for other purposes such as justification. This is accomplished by the use of a series of banks of stops, one of which is thrown up into the path of each of said operating parts on the return stroke.

55 In machines in this art thus far developed, which are based on the principles of opera-

tions above described, it is not possible to cast type differing widely in point size without manually disconnecting certain parts from the machine and substituting others. 60 It is one of the objects of this invention to provide a machine for automatically casting and setting type of different point sizes, the particular sizes for which the machine illustrated is adapted being 6 point, 8 point, 65 10 point, 12 point, 14 point and 18 point. This machine, however, is not limited to the above mentioned sizes, but may be arranged to cast type of 24 point, 30 point, and 36 point and higher sizes, in addition to the 70 sizes hereinbefore enumerated.

A second object of this invention is the provision of a simple line justifying mechanism, operative for controlling the casting of space quads in a line, irrespective of the 75 length of the line, whereby the width of the column of type cast and set up by my machine is not dependent on any limitation in the justifier mechanism.

A third object of this invention is the pro- 80 vision of a machine in which the type char-
acters may be set up and cast in the same order as the composition is made, this being
accomplished by combining a type perfor-
ing machine with the casting machine, and 85 by feeding the perforated tape directly from the perforator mechanism to the casting
machine, the justification perforations and the line cancelling perforations, if any, be-
ing made in advance of the beginning of the 90 line, by mechanism not necessary to be here
described and which is to be made the sub-
ject of another application.

A fourth object of this invention is the provision of a machine, which, by a simple 95 adjustment, may be converted into a type casting machine for producing a number of exactly identical characters to be used in various ways, as for instance, for work
which is to be set by hand. 100

A fifth object of this invention is the pro-
vision of an arrangement for the controlling 105 magnets, whereby any set of magnets, may readily be brought into position for in-
spection, repair, adjustment or replacement.

A sixth object of this invention is the pro-
vision of means for cooling the mold, by 110 forcing air therethrough, and additional ob-
jects, which need not be enumerated here,
will appear as the description of the inven-
tion progresses.

The provision of a machine which may be

set automatically to produce type of a number of different point sizes necessitates radical changes in structure. In other machines, when it is desired to change the point size of type to be cast, it becomes necessary to remove the matrix block, the mold and the plunger and stepped slide carried thereby, to adjust the galley and the galley head and to make certain other adjustments manually, all of which is laborious and time consuming, and consequently expensive. My improved machine is designed to make the necessary adjustments automatically, and to this end, certain changes are effected as in the matrix block carriage and the mechanism for operating the same, the mold and the parts cooperating therewith, the matrix centering arm, the galley head and the mechanism for operating the same, the mold plunger and its operating mechanism, and the pump, the above mentioned changes and others, as in the justifier, the magnets arrangement, the means for feeding the perforated strip and the means for cooling the mold, being more fully detailed hereinafter.

In the drawings,

Fig. 1 is a perspective view of the entire machine as it appears in position on the stand of the preferred form, in which a suitable strip perforating machine is foldably mounted. Fig. 2 is a top plan view of the assembled machine. Fig. 3 is a similar view in which the frame carrying the matrix holder has been turned back on its pivot to expose the underlying mechanism. Fig. 4 is a front view of the completely assembled machine showing the strip perforating device in the position it assumes when it is not in use and when it is folded out of the way. Fig. 4^a is a fragmentary side view of the strip perforating mechanism, showing in particular one of the foldable legs for supporting the perforator when it is drawn out into its operative position. Fig. 5 is a front view of the type casting and setting machine proper. Fig. 6 is a right side view of the same, showing in dotted lines, the three way circuit controlling switch. Fig. 7 is a partial vertical section of the machine viewed from the rear, the parts being in the position for the casting operation. Fig. 8 is a perspective view of the means for intermittently feeding and rewinding the perforated controlling strip. Fig. 9 is a perspective view of the matrix block holder and of the parts adjacent thereto and cooperating therewith. Fig. 10 is a horizontal section approximately through the center of one of the matrix blocks showing the means used for maintaining the inoperative matrix blocks in the initial position thereof. Fig. 11 is a perspective view, partly broken away, of the mold and of the parts adjacent thereto and cooperating therewith. Fig. 12 is a perspective view of the matrix centering arm, the slide

in which said arm is mounted and its actuating mechanism, and of the mold stepped slide and its actuating mechanism. Fig. 13 is a perspective view showing more clearly certain of the connections used in the mechanism shown in Fig. 12. Fig. 14 is a perspective view of the galley head, the parts adjacent thereto and the operating means for the same, showing particularly the means for shifting the pivot of the bell crank lever connected to the galley head. Fig. 15 is a vertical section of the same through said pivot. Fig. 16 is a top plan view of the mold and galley head and the parts adjacent thereto, showing the position assumed by the various parts just before said parts are adjusted for casting a new point size of type. Fig. 17 is a partial vertical section on line 17-17 of Fig. 16 and a front view combined of the rear mold plates showing a portion of the clamp for said plates and the metal conducting nipple to the mold. Fig. 18 is a horizontal section on line 18-18 of Fig. 17 showing in particular the removable pins for holding the inoperative plunger sections in place. Fig. 19 is a top plan view of the mold and its parts in the casting position thereof.

Fig. 20 is a similar view of the same in the type ejecting position thereof. Fig. 21 is a vertical section on line 21-21 of Fig. 19. Fig. 22 is a vertical section on line 22-22 of Fig. 20. Fig. 23 is a vertical section on line 23-23 of Fig. 20. Fig. 24 is a vertical section of the matrix block holder, the mold, galley and other parts on line 24-24 of Fig. 4. Fig. 25 is a vertical cross section of the matrix block holder showing the construction thereof. Fig. 26 is a front view of the matrix block holder and of the parts adjacent thereto in the casting position and Fig. 27 is a similar view of the same showing the position assumed by the parts while the point size of type is being changed. Fig. 28 is a top plan view of the magnets and of the controlling switch. Fig. 29 is a diagrammatic view of the wiring to the working and setting circuits. Fig. 30 is a similar view of the wiring to the circuit controlling the mechanism for changing the point size of type.

Fig. 31 is a top plan view and partial section of the locking and releasing means for the clutch governing the operation of the type size changing mechanism. Fig. 32 is a front view and partial vertical section on line 32-32 of Fig. 31 of a part of the same. Fig. 33 is a front view and partial vertical section on line 33-33 of Fig. 31. Fig. 34 is a top plan of a section of the controlling perforator strip. Fig. 35 is a bottom plan view of the justifier disc. Fig. 36 is a top plan view of the justifier pawl and ratchet. Fig. 37 is a top plan view of the device for locking and releasing the clutch which con-

trols the means for rotating the matrix block holder. Fig. 38 is a vertical section on line 38—38 of Fig. 37. Fig. 39 is a top plan view of the justifier and of the clutch which controls the end of the line mechanism and the connections therefor to the justifier and Fig. 40 is a perspective view partly broken away of the justifier itself.

Referring particularly to Figs. 1 to 7, the various operating mechanisms are supported directly, or by means of suitable brackets or bearings from the main bed plate 50, which is spaced and supported from the top of the stand 51, the various magnets used with my improved machine being arranged between said bed plate and the top of said stand. A table 52, upstanding from said bed plate 50 carries the tape feeding and rewinding mechanism and the electric circuit closing needles 53. While part of the stand 51 may be utilized for storage purposes and closed off by means of a door 54, the remainder of said stand may be used to house a strip perforating machine 55 of proper construction in such a manner that the said perforating machine may readily be folded out of the way when not in use. I provide, for this purpose, a pair of trolley guides 56 in which run the rollers 57, of the perforator 55.

The perforator, in its inoperative position, (Fig. 4) hangs by said rollers from said guide, being pushed back toward the rear of the casting machine as far as possible. To draw out the perforator into its operative position, it is pulled forward by means of the handle 58, then the lower end is swung upwardly about the rollers 57 as a pivot. Collapsible legs 59 of any well known design may then readily be slipped under the front end of the perforator for maintaining it in proper position and the strip 60 perforated as desired and fed directly to the casting machine for forming the type in the same order as the perforations are made. It will be seen that the perforations needed to set the justifier mechanism and the line cancelling devices must be made in the strip in advance of the perforations controlling the characters in that line. The mechanism for accomplishing this purpose is not shown here in detail since it is fully described in a subsequent application which will be filed shortly.

Before proceeding with the detailed description of the devices which operate to feed the perforated strip into the casting machine, I will describe generally the arrangement and function of the various shafts, cams, pulleys and clutches.

The main driving shaft 100 is suitably supported in the uprights 61 of the table frame 52 and carries a hollow shaft 102 whereon the cams, clutches, clutch sleeve and other means for actuating the various

instrumentalities which have movements necessarily repeated for the casting and setting of each character, and those which have movements repeated at the end of each line, are mounted. A second shaft 200, positioned in the machine substantially at right angles to the main shaft and supported in suitable bearings as 201 and 202 on the bed 50, carries the hollow shaft 203 on which are mounted the cams and other means for actuating the mechanisms which effectuate the change in the point size of type. Since the said change occurs comparatively infrequently, it is desirable to keep the shaft 200 and the mechanism operated thereby normally stationary. It is also advantageous to halt the operation of the casting and setting mechanism while the type size changing devices are being adjusted. To these ends, a clutch member 101, having three possible positions, is splined on the main shaft 100. The normal position of said member is that in which it engages the corresponding clutch member 103 on the hollow shaft 102. In such position, shaft 200 cannot be rotated but shafts 100 and 102 rotate as a unit. A second position of clutch member 101 is that in which it engages clutch member 104 attached to bevel gear 105 loosely mounted on shaft 100, whereby said gear and said shaft are operatively connected and are caused to rotate as a unit. Since bevel gear 204 on shaft 200 is continually in mesh with gear 105, this position of the clutch causes the type size changing mechanism only to operate and renders inoperative all the remaining mechanisms except the perforated strip feed device. The third position of the clutch member 101 is between members 103 and 104, in which position it engages neither of the other members, and consequently none of the machine parts are operative excepting the feeding device for the perforated strip. The parts operative at the end of each line are loosely mounted on hollow shaft 102, being connected thereto for operation by a suitable one revolution clutch 1105 (Figs. 2, 3, and 39).

During that time in which the type size changing mechanism is selecting the proper matrix block, it is desirable that all of the remaining parts of the machine excepting the feed for the perforated strip be halted. This is accomplished by arranging all of the type size changing mechanism excepting the block holder rotating device on hollow shaft 203, and interposing a clutch 211 between said shaft 203 and the mechanism for actuating the matrix block selecting parts.

I prefer to make the bevel gear 204 twice the size of gear 105 so that shafts 200 and 203 rotate once for every two revolutions of shafts 100 and 102, one half of a revolution of said shaft 203 serving to set the proper stops and to adjust the type size 130

change devices to the new size of type, and the other half of the revolution being used to bring the actuating mechanism back to its initial position. This arrangement permits control of the matrix block selecting mechanism through perforations in the paper strip, since one perforation effects a one-half revolution of shaft 200; the next perforations disconnect shaft 200 from shaft 203 and connect it to the matrix block changing mechanism, until the proper block is in position; whereupon shaft 200 is reconnected to shaft 203 and the remaining half revolution returns the parts to casting position. The next perforation operates to disconnect shaft 200 from shaft 100. The advantages of this arrangement will be more clearly brought out in the detailed description of the type size changing means hereinafter set forth.

For rotating the driving shaft 100, power is supplied thereto from any suitable source as by the motor 106, which drives the pulley 107 on shaft 100 through the belt 108, a hand wheel 109 being mounted on said shaft 100 for the manual manipulation thereof when desired.

The detailed description of my improved machine which follows will be treated under the following main divisions: the perforated strip feeding and rewinding mechanism; the matrix block holder, and its rotating mechanism, and the matrix centering arm; the mold and the mold plunger; the galley head; the pump; the justifier; the wiring and the arrangement of the switches and magnets.

The strip feeding and rewinding mechanism.

Referring especially to Fig. 8 and incidentally to Figs. 1, 2, 4, 5, and 6, the perforated controlling strip 60, as it comes from the perforator 55, may be inserted between the cylinders 62 and 63 of a slack provider, or said strip may first be wound up on a spool 64, from which it is fed through the slack provider to a rewinding spool 65. In either case a portion of the tape is always kept in a slackened state to prevent tearing or other mutilation thereof during the feeding operation. The slack provider comprises the cylinders 62 and 63 mentioned, connected by suitable links 67 tightly secured to the lower cylinder 63 for preventing the upper cylinder from swinging, said cylinders being given a reciprocatory motion by means of rod 68, which is actuated by lever 69 through cam 70 on shaft 100. (Fig. 6.) Said lever 69 is pivoted at one end to bracket 71 suitably supported from the under side of table 52, a branch arm 72 of said lever carrying roller 73 to engage said cam 70.

From the slack provider the strip 60 is threaded under the index head 74, contain-

ing the spring pressed contact making needles 53, the under side of said index head being cut away at 76 to allow said strip to pass therethrough. (Fig. 8.) The index head block 77 is shaped to allow of its vertical reciprocation in suitable grooves cut in the frame 66, in which are set the mercury wells 78 of the usual type which need not be described here, the wires in cable 79 (Fig. 6) connecting the needles 53 electrically to the movable three way switch 80. The index head block 77 is connected to the lever 81 by means of the extending arm 82, said lever being pivoted at 83 on frame 66, and having a tension spring 84 secured to one end thereof. The pawl carrying arm 85 actuated by cam 86 on shaft 100 has a pin 87 fixed thereon, which pin, on its upward movement strikes the free end of lever 81, thereby causing said lever to rotate about its pivot 83 to draw the block 76 carrying the contact needles downwardly against the action of spring 84. Those of said needles which happen to register with a perforation in the strip 60 pass through said strip into the mercury wells thereunder, whereby the electric circuit is closed to certain of the members of the switch 80 and therethrough certain parts of the mechanism are caused to operate, as will be more fully described hereinafter.

From under the index head, the strip 60 is passed around the roll 88, which has pins 89 projecting therefrom designed to enter the feed holes 90 of said strip (Figs. 8 and 34) for positively feeding said strip on the rotation of said roll. A shaft 91 carried by bracket 92 on table 52 revolvably supports said roll and has mounted thereon at one side of said roll ratchet wheel 93 and on the other side of said roll, gear wheel 94. For intermittently rotating said roll 88 to give strip 60 a step by step motion, a pawl 95 is mounted on shaft 96 of the pawl carrier 85, said pawl engaging said ratchet wheel on the upward movement of said pawl carrier, and causing said ratchet wheel to rotate sufficiently on each revolution of cam 86 to feed said strip an amount equal to the distance between centers of successive perforations. As a guide for said pawl carrier, a suitable groove is made in bracket 71 through which said carrier passes and a cover plate 97 attached thereover. A second pawl 98 supported on stud 99 from bracket 92 and held by the bent flat-spring 100 in contact with ratchet wheel 93, serves to prevent rotation of said wheel in the wrong direction.

To halt the feeding of the strip 60, it is only necessary to rotate feed pawl 95 about shaft 96 until it becomes disengaged from wheel 93, using the milled end of 108 of said shaft 96 for that purpose. The effect of this simple disengagement is to keep the strip 130

stationary, whereby those needles which have penetrated the strip to make contacts are allowed to remake the same contacts repeatedly, so that the characters governed by 5 the perforations penetrated will be cast repeatedly on every revolution of the main shaft 100, and the machine thereby converted temporarily into an ordinary type casting machine.

10. Instead of allowing the strip to become torn, entangled or lost after it has passed the index head, I provide a spool 65 and a suitable support therefor on which said strip may be rewound for the preservation 15 thereof. A bracket 197 on table 52 carries a short shaft 196 on which gear 195 is mounted, said shaft 196 being flattened at its inner end to grip the roll 65. A similar short shaft is provided at the end of bracket 20 66 for carrying the feeding spool 64 thereon. On the side of brackets 197 and 66 opposite to that on which shafts 196 are mounted, a stud 1195 tapered at its inner end is carried, a compression spring 194 25 acting between collar 193 of stud 195 and extension 192 of brackets 197 and 66 to urge said studs inwardly into the spools mounted thereon.

The operation of the strip feeding device is as follows: The strip having been threaded from spool 64 through the slack provider, under the index head and over the pins of roll 88, and the strip carrying spools having been mounted on shafts 196 30 and studs 1195 by inserting said studs into suitable openings in said spools, pressing said studs back against the action of springs 194 until shafts 196 can enter suitable slots in said spools, the motor 106 is started. 35 The slack provider is thereby reciprocated, drawing off a portion of the strip from spool 64, and block 77 is also reciprocated vertically allowing needles 53 to penetrate the strip perforations to make the proper contacts. Arm 85 is also reciprocated 40 thereby turning feed roll 88 to advance the strip and take up some of the slack which may have been allowed to form between the index head and said roll, and spool 65 is 45 rotated through gears 94 and 195 to rewind the strip.

The matrix block holder and its operating mechanism. Figs. 1, 2, 4, 5, 7, 9, 24, 55 to 27, referring especially to Fig. 9.

In previous machines of the type under discussion, a single matrix block containing a series of matrices arranged in rows for a font of type of the same point size, was 60 mounted on a carriage capable of horizontal reciprocation for selecting the row, the desired matrix in the row for a particular character being selected by moving the matrix block across the carriage.

65 In my improved machine, I provide a

matrix block holder 300 capable of carrying a series of matrix blocks each designed to allow the casting therein of type faces of a point size differing from that of the other matrix blocks. The form of the matrix 70 block holder shown is that of a hexagonal prism, whereby the machine becomes adapted, with the additional changes soon to be described, to cast automatically type of six different point sizes, though it is obvious 75 that the number of different point sizes of type which can be cast by a machine embodying the principles of my invention is not limited to the number of six, but may be increased or decreased by the use of a 80 polygonal prism of the proper number of sides. A carriage 301 supports the holder 300, as will be presently described, said carriage having suitable tongues 302 adapted to run in the grooves 303 of the hinged 85 frame 304. The matrix block on the lowermost face of the holder 300 at any time is the one which is operated to have type cast therein; the row in which the matrix character desired is located being selected by 90 the rearward movement of said carriage in said frame 304 by means of the tension spring 305 attached at one end to pin 306 on said frame and at the other end to the pin 307 on said carriage, said movement of 95 the carriage being controlled in the usual manner by the lever 308, (Fig. 2) pivoted at 309 and engaging the cam 110 on shaft 102. The forward movement to its initial position is given to said carriage by said 100 cam 110 through said lever 308 acting on the extension 1311 of said carriage, while the rearward row selecting movement is given to said carriage by said spring 305 when permitted by said cam, the movement 105 continuing until stopped by one of the bank of stops 311, which stops are controlled by the proper perforation in the strip 60, acting to energize the proper one of magnets 312.

The matrix block holder itself (Figs. 9 and 25) comprises preferably a pair of hexagonal end plates 313 connected at the corners by angularly shaped members 314, held by screws 388 to said plates and having suitable grooves 315 in which the tongues 316 of matrix blocks 317 may be moved between plates 313. A ratchet wheel 318 having a hub 319 is secured to one of said end plates 313, while a similar ratchet wheel 320 having a central opening 321 is secured to the other of said plates. A cut 322, (Fig. 24) is made in the carriage 301, in which the teeth 323 of said ratchet wheels rest for supporting said matrix holder. To provide additional support for said holder and to accurately position said holder on said carriage, six pairs of tapered holes 324 are made in each of ratchet wheels 318 and 320 and a pair of centering pins 325, supported 110 115 120 125 130

- in bearings 326 on each side of carriage 301 are arranged to register with and normally to enter a pair of said tapered holes, which are suitably arranged on said ratchet wheel 6 so as to register with said pins when any one of the matrix blocks is in its lowermost position. Each of said pins 325 carries an upwardly projecting finger 327 pulled by a spring 328 toward said holder for normally holding said pins in said holes. When the holder 300 is to be rotated on the carriage for presenting a new matrix block to the mold for casting type of a new point size, the pins 325 are withdrawn from the holes 324 by means of a lever 329 pivoted at 330 on the long arm 331 of the bell crank lever 334. Rollers 332 are arranged at the extremities of said lever 329 for engaging the upstanding fingers 327, while the downwardly extending arms 333 each forming one of the branches of the bell crank levers 334, are bent to be suitably secured to roller 335 (Figs. 24 and 26) which engage the surface of the cam 206 on shaft 203. Rotation 25 of the shaft 203 at the proper time causes cam 206 to rock the bell crank lever 334 whereby lever 329 is drawn away from the holder 300 and the rollers 330 are pressed against the upstanding fingers 327 to withdraw the pins 325 through bearings 326 and out of the holes 324, and resulting in the release of said holder from the carriage on which it rests. A safety pawl 300' (Fig. 24) pivoted at 302' on the carriage 301, and 30 pulled by the spring 301' into engagement with the ratchet wheel 320, serves to prevent the rotation of said holder in the wrong direction. Before the holder can be rotated, however, the operative matrix block must be 40 separated from the mold.
- The most convenient way of doing this is to raise the entire frame 304 a distance sufficient to allow the holder to be rotated without interfering with any of the mold parts 45 thereunder. Said frame is hinged at its rear end by means of the adjustable tapered hinge pins 335 to the bracket 336 upstanding from the machine frame, the front end of said frame being supported normally by the upper faces of the bearings 337 suitably connected to the frame of the machine as at 338, Fig. 24. The rods 339 having shoulders 340 thereon against which the compression springs 341 act, pass through said 55 bearings, and in their normal position, are just long enough to touch the under side of the frame 304. The lower ends of said rods 339 rest on the rollers 342 connected by shaft 343, which shaft is operated by bent lever 344 through a cam on shaft 203, said lever having one end thereof mounted on said shaft 343 and having the other end thereof pivoted in upstanding bracket 345. The rotation of cam 207 rocks the lever 344 60 above its pivot in bracket 345, raising the rear end of said lever and therethrough the shaft 343, rollers 342, rods 339 and the front end of frame 304.
- Each of the matrix blocks 317 has a series of tapered holes 346 made in the surface 70 thereof opposite to that in which the matrices 347 are made, for the purpose of accurately centering any of the matrices above the mold, in order to cast the face of the type in proper relation to the body of 75 said type. A vertically reciprocating centering arm 348 (Fig. 7) supporting a spring pressed centering pin 349 tapered at its lower end is usually used for entering one of said matrix holes 346 to center the matrix 80 thereunder accurately above the mold and to put pressure on the matrix block for closing any small space which may be left between the upper end of the mold and the matrix block so that smooth type may be 85 cast.
- It will be seen that when it is desired to lift the frame 304 for the purpose of allowing the matrix block holder 300 carried thereby to be rotated, said centering pin 349 90 should first be removed from within the matrix holder, to prevent interference with said matrix when the holder is raised; and a change in the usual construction of the support for said pin is therefore desirable. I 95 provide a centering arm holder 350 (Fig. 12) in which the centering arm 348 and the centering pin 349 are mounted for vertical reciprocation by means of the forked bell crank lever 351 acting on collar 354 against 100 the action of spring 356, said lever being pivoted at 352 on the upstanding frame lug 353 and operated through rod 355, slide bar 1356 roller 357 and cam 111 on shaft 102. The bolt 358 passing through slot 359 of bar 105 1356 and inserted in the frame of the machine acts as a guide for said bar.
- While the vertical reciprocation of the centering arm and pin takes place every time a new character is selected on a given matrix 110 block, the horizontal reciprocation takes place only when a new matrix block is to be selected for changing the point size type. In that event, the entire centering arm holder 350, which has a suitably shaped base 360 to 115 fit into the T-slot 361 of the machine frame (Fig. 12) is horizontally reciprocated by the bent lever 362 pivoted at 363 (Fig. 2) and connected by link 363 to cam lever 364 which is pivoted at 367 and is operated by the cam 120 366 on shaft 202. Fig. 26 shows the position of the centering arm and holder inside of the matrix block holder, while Fig. 27 shows the position of the same parts after they have been withdrawn from said matrix block 125 holder. The forked end of lever 351 is in its uppermost position when the centering pin is not engaging one of the tapered holes in the matrix block, as is the case when a change of type size is about to be effected, 130

and the holder 350 withdrawn from the matrix holder 300, said lever 351 remaining in its uppermost position during the change of type size. When the centering arm holder 350 is brought back into the matrix holder by lever 362, the centering arm 348 is inserted into the fork of lever 351 again, collar 354 positioning itself under said lever ready for the matrix centering operation to 10 be repeated. A stationary pin 1350 (Fig. 12) in the machine frame serves to accurately locate the base 360 of the centering arm holder 350 in its position inside the matrix block holder while a vertically reciprocating 15 pin 1360 (Fig. 7) carried by the arm 1369 pivoted in the shaft 425, is thrown up by the spring 1362 attached to said arm 1369 to engage the left end of said base 360 for preventing the holder 350 from leaving its matrix centering position until said pin 1360 is withdrawn. The withdrawal of said pin is accomplished when the magnet 1363 is energized through a suitable perforation in the strip 60 immediately after the type size 20 25 change clutch has been operated to connect shafts 203 and 100. When the centering arm is out of the matrix block holder, pin 1360 is depressed by the base 360 and cannot interfere with the movement of said base until the matrix centering position is reached, at which time the said pin 1360 is pulled up into operating position by the spring 1362.

Before proceeding with the description of the remaining steps which must be taken to 30 effect a change in the size of type, and the mechanism provided therefor, it will be convenient here to describe briefly the device for selecting the individual character of a row in the matrix block, which device is 35 somewhat similar to those in previous use. A branch arm 368 of row selecting lever 308 is secured to the hook arm 369 (Figs. 2 and 7) which engages a groove in the under side 40 of the operating matrix block, said hook arm operating in the guide 370. A similar hook arm 371 operating in the guide 376 engages 45 another groove in the under side of the matrix block, and is drawn toward the left by means of a spring 372 attached at one end to 50 a pin 373 on said hook arm 371 and at the other end to a pin 377 on the machine frame, cam 110 acting to cause said hook arm 369 to draw the matrix block to the right into 55 its extreme position immediately after each 60 character has been cast, while spring 372 draws said matrix block to the left, being allowed to do so by said cam 110 after said matrix has been first moved to the right, until hook arm 371 is stopped in its path by the 65 proper one of stops 374 thrown up by magnets 375, the proper one of which is energized when the contact is made through the character perforation on the strip 60. It will be seen that if none of the stops 374 is thrown up into the path of hook arm 371, the

spring 372 will draw the matrix block into an extreme position to the left of the matrix holder, which is the position in which said matrix block is left when a change in the type size is about to be effected.

Referring to Fig. 10, the inoperative matrix blocks 317 are maintained in their position at the extreme left of the matrix holder 300, (called the initial position) by means of a pair of dogs 378 pivoted at 379 in a cut away portion of the grooves in members 314, a tension spring 380 serving to hold each of said dogs in engagement with said matrix block, without interfering materially with the character selecting movement of 80 said block in said members 314. On the rotation of the matrix block holder for changing the point size of type and for the selection of a new matrix block, the block formerly in operation is simply rotated out of 85 engagement with hook arms 369 and 371, while the new block being accurately held in its initial position at the extreme left of the block holder, is rotated into engagement with 90 said hook arms.

It will be recalled that the steps affecting the matrix block when a change in the type size is to be made, take place in the following order. The block in operation is brought to its initial position, the centering arm and 95 pin together with the holder therefor are removed from the inside of the matrix block holder, the front end of the hinge frame 304 is raised by means of the rods 339, and the pins 325 holding the matrix block holder down on the carriage 301 are removed thereby releasing said matrix block holder. After these steps have been completed, there yet remains the supporting of the matrix block holder during its rotation, and the rotation 105 of said block holder for the selection of a new matrix block, which will now be described.

The frame 304 is raised by the rods 339 a distance sufficient to bring the tapered stud 110 381 opposite the opening 382 in the hub 319 (Figs. 26 and 27). A horizontal movement is now given to said stud to cause it to enter said opening for supporting the matrix block holder during the rotation thereof, by 115 means of lever 384 pivoted at one end on post 385 upstanding from bed plate 50 (Fig. 1) and actuated by cam 386 on shaft 203, said lever 384 being secured at its other end to the base 387 of arm 383 said base being 120 lightly mounted in guide 388, and held by spring 387 against movement to the right.

It might be advisable to explain at this point that the type size changing shaft 203 125 is allowed to move only through a half revolution at a time, the first half of the revolution being effective to set the various parts in preparation for the selection of the frame 300 block by the rotation of the new 130

matrix, and the second half of the revolution being effective to restore the parts to their various initial positions, the description of the means for controlling the shaft 6 revolution being temporarily postponed. The reason for allowing only a half revolution of shaft 203 at a time is that in the selection of a new matrix block, it may be necessary to rotate the block holder through 10 any one of five different angles depending on the new size of type desired. It is therefore desirable to halt the operation of all the other mechanisms until the desired matrix block is selected, after which the parts 15 may be restored to their various initial positions and the casting of type resumed.

The mechanism for rotating the matrix block holder comprises a pair of pawls 389 engaging the ratchet wheels 318 and 320 20 each of said pawls being mounted on rearwardly extending arms 390 of the branch 391, said branch being positioned along the front of the machine and forming part of the long rearwardly extending lever 392 pivoted at 393 from the extension 394 of the up-standing bracket 336. A downwardly extending branch 395 (shown in full lines in Fig. 24) of said lever 392, which is shown dotted in Fig. 24, terminates in a roller 396 25 in engagement with cam 207 on the sleeve 200'. Each of the pawls 389 is suitably secured to one of the arms 390 as by a screw 397 attached to the pawl and operating in the slot 399 of arm 390, the compression 30 spring 398 serving to urge the pawl into engagement with the ratchet wheel.

At this point, it is convenient to describe the construction and operation of the two clutch mechanisms which are instrumental 40 in controlling the type size changing devices. When the change is about to take place from one size of type to another, the slideable clutch member 101 on the main shaft 100 is first moved toward the front until the tooth 45 112 thereon engages a similar tooth 113 on the member 104. The mechanism for imparting this motion to the member 101 comprises (Figs. 3, 6, 31 to 33) in part the forked bell crank clutch lever 114 engaging the 50 clutch member 101 and pivoted at 115 (Fig. 6) and the magnet controlled operating lever 116 (Fig. 31) pivoted at 117 and operated by the clutch trip magnet 118 when said magnet is energized at the index head 55 through a suitable perforation and consequent circuit closing contact to said magnet.

Since the selection of the matrix block desired may require from one to five revolutions of the shaft 200, the clutch member 101 60 should be retained in its shifted position until the type size change is completed. For this purpose a spring pressed pin 119, having a tapered end 120 adapted to enter the tapered hole 122 on the lower extremity of 65 the bell crank lever 114 and having a head

121 at the other end, is slidably supported in the bearing 123. The rocking of the bell crank lever 114 to throw the member 101 into engagement with member 104, raises that end of said lever in which the hole 122 is made, a distance sufficient to allow the tapered pin 119 to enter said hole, urged thereto by the spring 124, whereby the clutch members are locked in position.

The clutch member 211 slidably mounted 70 on shaft 200 must be shifted to engage the clutch member 212 on a sleeve 200' mounted on shaft 200 to set the mechanism for rotating the matrix block holder in motion. The forked bell crank lever 213 engages said 80 clutch member 211 and is pivoted at 214 on upstanding lug 215, said lever having a tapered hole 216 in its lower left extremity (Fig. 5) into which the spring pressed pin 217 (similar to pin 119) having one end 218 85 tapered, and having a head 219 at the other end, may enter, when said lever has been rocked through a sufficient angle, said pin being supported in bearing 221. A flat spring 223 serves to urge said bell crank 90 lever normally into engagement with cam 386. (Fig. 3) the teeth 212' and 386' respectively coacting to lock said clutch members together. In this position, shaft 203 is rotated and the type size changing mechanism 95 on said shaft is actuated.

The rotation of the shaft 203 is allowed to continue only for a half revolution as above described, at which point the parts are all set to allow the rotation of the inmatrix block 100 holder to begin for the selection of the new matrix block.

Before the rotation of said matrix block holder is started, the various parts operated through shaft 203 are halted by withdrawing the clutch member 211 from engagement with the combined cam and clutch member 386, thereby operatively disconnecting said shaft 203 from shaft 200, after the half revolution of shaft 203 is completed.

This is accomplished by means of the magnet 220 which is controlled by a suitable perforation in the strip 60, and which when energized pulls down the trip arm 222 115 (Fig. 37) suitably guided in the bed plate 50, said arm 222 resting on the horizontal member of the bell crank lever 213 and depressing said member against the action of the flat spring 223 to rock said lever to shift 120 the clutch member 211 into engagement with the clutch member 212 to cause the teeth 224 and 225 of said members respectively to engage, and to bring the hole 216 of said lever opposite pin 217 whereupon said pin 125 enters said hole and locks the clutch members 211 and 212 together, causing the sleeve 200' to rotate and causing the holder rotating mechanism above described to begin operating.

The rotation of said holder for the selection of the new matrix block continues for as many rotations of shaft 200 as are necessary to effect the change in the matrix block, 5 blank spaces being left in the strip 60 during this interval so that no other parts of the machine operate. As soon as the proper number of turns of the block holder 300 have been made, it becomes necessary to re-

10 store the parts to their initial positions.

The pin 217 is therefore withdrawn from the hole 216 in the bell crank lever 213 by means of a horizontal lever 226 engaging the head 219 of said pin and pivoted at 227 15 to the bed plate 50. The bell crank lever 228 (Fig. 38) pivoted at 229 and passing through the slot 231 in the bed plate 50 is operated by the magnet 230 when energized through a suitable perforation in the strip 20 20 60, and engages the rear end of the lever 226 to cause said lever to pull pin 217 away from lever 213 against the action of spring 232, the flat spring 223 secured to bed plate 50 acting to rock said bell crank lever 213 to 25 cause said lever to separate clutch members 211 and 212 thereby reconnecting shafts 200 and 203 and allowing the rotation of shaft 203 to continue for the remaining half revolution to bring the various parts back to 30 their initial positions, at the same time disconnecting sleeve 200' from shaft 200 so that the holder rotating mechanism ceases to operate.

Immediately after the initial positions of 35 the type size changing mechanisms have been reached, the clutch member 101 on the main shaft is disengaged from the member 104 for disconnecting shaft 200, by removing the pin 119 from the hole 122 in the forked 40 clutch lever 114 whereby the flat spring 125 on bed plate 50 depresses the horizontal arm of the bent lever 126, pivoted at 127 to cause said lever 126 to depress the horizontal arm of the clutch lever 114 and shift clutch 45 member 101 away from member 104. The above described movement of pin 119 is effected by the lever 128 engaging the head 121 of the pin 119 and pivoted at 129 for horizontal oscillation, a bell crank lever 130 50 pivoted at 131 (Figs. 31 and 33) serving to operate said lever 128 when the magnet 132 is energized at the proper time.

Referring to Figs. 6, 31 and 32, it will be recalled that the switch 80 may be shifted 55 automatically to close either one of the working, setting or type size changing electric circuits at a time. When the type size changing mechanism is thrown into operation, it is necessary at the same time to 60 throw the switch 80 to close the corresponding electric circuit to the magnets controlling the change.

When the magnet operated lever 116 raises 65 clutch lever 114, the bent lever 126 is rotated about its pivot 127, the vertical arm

of said lever 126 engaging one of the arms of bent lever 133 pivoted at 134, thereby imparting a horizontal movement to the downwardly extending arm of said lever 133 which is connected to the switch arm 70 75 135. Said switch arm engages the angular member 136 on the switch plate 137 and moves the switch members 80 the proper distance to close the type size changing circuit, as required.

To recapitulate, the operation of the mechanism for selecting a new matrix for a new point size of type is as follows:

Clutch member 101 being shifted and temporarily locked in place, the type size 80 changing switch is closed, magnet 1363 is energized to lower pin 1360, shaft 203 is rotated through a half revolution, the centering arm 348 and its holder are withdrawn from the inside of the matrix block 85 holder, the front end of frame 304 is raised, the pins 325 withdrawn from the ratchet wheels on the block holder, to release said holder for rotation, the stud 381 moved into the hole 382 of the holder for supporting 90 said holder, the clutch member 211 shifted into engagement with member 212 and out of engagement with member 386 to halt the operation of all but the mechanism for 95 rotating the matrix block holder, which is then rotated until the desired block is selected after which the clutch member 211 is shifted back to its initial position, the shaft 203 rotated through the remaining half of its revolution whereby pin 325 is caused to re-enter the centering holes 324, the supporting 100 stud 381 is removed, the frame 304 is lowered and the centering arm and holder caused to reenter the matrix holder, after which clutch member 101 is shifted back 105 in position to actuate shaft 102 and the type casting mechanism.

The mold, mold plunger, the step slide, the metal pump and the operating mechanism therefor (Figs. 3, 5, 7, 11 to 13, and 16 to 24, especially Figs. 11 and 16 to 23).

It is obvious that to provide a properly sized space for casting type bodies of different point sizes, the casting space as 400 115 (Fig. 11) must be adjustable not only from front to back as in prior machines in this art for casting different face sizes of the same point size, but also must be adjusted from side to side. This is provided for by 120 the use of a mold plunger 401 variable in thickness in addition to the use of means for halting the plunger at many different points in its forward movement, to correspond to the different face sizes of characters for each of the point sizes of type which may be cast by the machine. I vary the thickness of the plunger to change the point size of type by the addition or subtraction 125 of plunger sections as needed, and I vary 130

the frontward position of said plunger by means of a slide 402 carrying a set of notched steps thereon.

The usual up and down motion is given 5 to the mold for separating the type face cast in the matrix from the matrix block, and the usual sideways movement is given to the mold jaws 403 and 404 and to the plunger for ejecting the finished type from the mold.

10 Specifically, the usual vertical reciprocating bracket 405 having the upstanding lips 407 and 408 thereon carries the entire mold, the lowermost member 406 of said mold resting on the upper face of said bracket 405. Suitably secured to said member 406 is the main mold plate 409 on which

15 the mold jaws 403 and 404 are slidably mounted, the flanges 410 of said plate serving to guide said jaws in their movement.

20 A stationary rear mold plate 411 has a tongue 411' (Fig. 17) near the lower portion thereof, and the mold plate 412 has a groove 412' therein, in which the tongue 411' is adapted to fit slidably to form a halved

25 lap joint, said rear plates being separable for adjusting the space 413 between them in conformity with the point size of type being cast.

Said plates rest on the upper face of 30 bracket 405 one of said plates 412 being arranged for slidable movement between the lowermost plate 406 and the lip 407 of bracket 405, the front faces of said plates serving as guides in cooperation with flanges 35 410, for the mold jaws. Said mold jaws 403 and 404, are normally urged toward each other by means of the compression springs 414 acting against the heads 415 of the rods 416, said rods passing through jaw 403 and 40 lying in a slot 417 of jaw 404.

The molten metal is forced through the pipe 418 (Fig. 7) in a manner hereinafter described, thence through the nipple 419 which has the customary up and down motion, and which passes through suitable openings in plates 406 and 409 into the casting space 400. Figs. 11 and 19 show the position of the mold jaws during the casting operation from which it is seen that the 45 movement of said jaws toward the right must take place before the cast type can be ejected. Figs. 16 and 20 show the position assumed by the mold parts during the ejecting operation, the finished type being received on the galley 420, the upper surface of which is at the same level with the upper surface of plate 409 when the entire mold is in its lowermost position. This makes possible the movement of the finished type from 50 the casting space 400 through the space 413 between the rear mold plates 411 and 412 into the galley, without changing the level of said type in transit. The movement of the mold jaws to the ejecting position is effected by means of the upstanding arms 421

(Fig. 7) having the usual adjustable pins 427 at the upper ends thereof for engaging said jaws, said arms being secured to the sliding block 422, said block being mounted in suitable guides in the machine frame, and 70 being operated from cam groove 155 in cam 160 on shaft 102, through the roller 423 on lever 424 pivoted at 425, the upper end of said lever 424 operating in a suitable slot 426 in said block 422.

75 The mold jaws are made hollow to allow said jaws and the surrounding parts to be cooled by a current of air forced through the air pipes 428 flexibly connected to said jaws by means of a suitable blower 157 driven 80 through gear 158 on shaft 100 and gear 159 meshing therewith. (Fig. 3)

The rear end of the plunger 401 forms the front face of the type body mold and is given a reciprocatory motion from front to 85 back. The rearward movement of said plunger against the action of spring 433 operates to eject the cast type in the usual manner, while the forward movement of said plunger given thereto by spring 433 is 90 limited by the selected step on the stepped slide 402, whereby the face width of the type is determined. The rearward movement of said plunger is given thereto by the arm 429 (Fig. 3) of the lever 430 pivoted at 431, 95 through the roller 432 acting in the groove in cam 160 on shaft 102, while the spring 433 acts to draw said plunger forward into engagement with the proper step of the stepped slide.

100 As is usual in this type of machine, the plunger is given a stroke of extraordinary length after the last type of a line has been cast (Figs. 2 and 3) by means of link 434 secured at one end to pivot 431 and at the other end 435 pivoted to lever 436, operated from cam 161 of the end of the line clutch, and pivoted at 436.

105 The means for determining the width of the type body, as pointed out above, is the stepped slide 402, in which is cut a series of notches corresponding in depth to the widths of the type. There are six of such sets of type corresponding to the six point sizes of type which may be cast in the type of the 110 machine illustrated. Said slide is made angular in cross-section, the steps or notches being cut on the thinner flange 438 while the notches 437, on the under side of the thicker flange 439 are spaced apart a distance equal 115 to the length of a set of steps for a given point size of type, said flange 438 being guided for slidable movement in bracket 440. Said slide 402 is normally urged toward the left by means of a flat coiled spring 441, secured at one end to pin 442 on said slide, and at its other end to shaft 443 (Fig. 5) suitably supported from the machine frame, said spring passing over a suitable roller 444 for changing its direction, the left end of said 120

125 130

slide being slidably mounted in a suitable slotted guide 444' mounted on the frame of the machine. For selecting the desired one of the various sets of steps in said slide, the 5 proper one of stops 445 is thrown up by a suitable magnet, into the path of said stepped slide when said slide is drawn to the left by spring 441 for the selection of a new point size of type.

10 Normally, however, the slide 402 is given a reciprocatory motion confined entirely within the limits of one set of steps. For this purpose, a bell crank lever 446 (Figs. 11 and 12) on a shaft 447 mounted in bearing 448 carries a lever 449 suspended therefrom at 450, a pin 451 at the rear end of said lever 449 being arranged to enter the proper one of notches 437 on said slide. A spring 451' tends to draw levers 449 and 20 446 together for raising the rear end of lever 449 to cause said pin 451 to enter said notch 437. The arm 452 of bell crank lever 446 is connected to a bent lever 453 pivoted at 454 and having a roller 455 operated by lever 430, 25 said bell crank lever being given a movement toward the right through cam 160, levers 430 and 453, for bringing the slide to an initial position at the extreme right of said movement, spring 441 serving to draw 30 said slide and the bell crank lever in engagement therewith toward the left, until the finger 456, on the same shaft 447 on which said bell crank lever is mounted, strikes the proper one of a bank of stops 457' thrown up into the path of said finger in the usual manner by a magnet controlled from strip 35 60.

The plunger 401 comprises a series of nesting sections, 458, 459, 460, 461, 462 and 40 463, having comparatively heavy front ends, the rear portions of said sections being made in thickness an amount equal to the size of 6-point; 2 point, 2 point, 2 point, 2 point and 4 point type respectively. In the change 45 from one point size of type to another, it will be recalled that plunger sections may be added or subtracted to increase or to decrease the thickness of the plunger, which thickness, as is usual, determines the point 50 size of type to be cast, by causing the jaws 403 and 404 to be separated by the amount of the plunger thickness. For instance, if six point type is to be cast, plunger section 458 alone is used. For eight point type, sections 458 and 459 are used, it being understood that additional plunger sections are added to the right as required. Tapered holes are made in the front heavy ends of the plunger sections, a suitable tapered pin 60 464 (Fig. 11) being carried by the stationary plunger guide 466, normally urged to enter said holes by a spring 465, said sections being accurately located relatively by said pin, and being supported by said pin in such 65 a manner that said sections act as a unit.

Figs. 19 to 24: A bracket 487, having a U-shaped top suitably supported from the frame of the machine, supports a series of spring pressed rods 468, said rods being preferably integral with and extending 70 downwardly from the rod heads 469 or blocks arranged to be supported in said bracket top. Each of said rod heads 469 is designed to underlie one of the plunger sections and is shaped similarly to the corresponding plunger section, said head 469 having tapered pins 470 extending upwardly therefrom and adapted to fit into the tapered holes 471 in each of the plunger sections. 75

Suitable openings 472 and 473 are made in mold plates 409 and 406 respectively to allow plunger sections 459, 460, 461, 462 and 463 to drop therethrough when the point size of type is to be changed, said sections being 80 guided in their downward movement by the walls of said openings 472 and 473 until the pins 470 enter the holes 471 to hold the plunger sections in place. In their inoperative 85 positions, the rear end of the various plunger sections rest on the upper surface of bracket 405 and move up and down therewith, said ends being held securely by the tapered spring pressed pins 474 (Fig. 18) in suitable holes 475 in said sections, suitable 90 provision being made for withdrawing said pins 474 from said holes 475 when a change 95 in the point size of type is to be made to permit the increase or decrease of the number of sections in the inoperative position. 100

Referring to Fig. 16 which shows the mold and allied parts in the position assumed while change in the point size of type is being made, attention is called to the fact that a change in plunger thickness and necessary changes in the mold parts are made 105 preferably after the casting of a line has been completed, at which time the mold plunger has completed the ejection of the last type in the line and has been drawn 110 back against the stepped slide 402. It will be recalled that the mechanisms actuated from shaft 203 are shifted from their various set positions to their released positions during the first half revolution of said 115 shaft, then halted till the proper matrix block is selected, after which the second half revolution of shaft 203 operates to reset the various mold, plunger and stepped slide parts to their new positions. After the mold plunger has been drawn back against the stepped slide by the spring 433, the clamp yoke 476 pivoted to lever 477 at 478 carrying a pin 479 pivoted thereto at 480 and having a rounded end 481 (Fig. 18) for 120 engagement with the rear surface of rear mold plate 411, is shifted by the action of spring 483 which draws lever 477 and the rear end of yoke 476 to the left, thereby 125 releasing rear mold plates 411 and 412 for 130

allowing relative motion of said plates, the cam 285 on the hollow shaft 203 permitting the arm 482 of lever 477 which is pivoted at 484 to the mold plate 409, to take such motion toward the left.

Simultaneously, the tapered pins 485 and 486 normally held in their foremost position by springs 487 and 488 respectively, are pushed rearwardly by the rollers 489 and 490 on the U-shaped arm 491 (Fig. 11), said arm being guided by suitable slots in the guides 492 suitably secured to mold plate 409. Motion is imparted to said arm 491 by link 493 which has a roller 494 at the front extremity thereof in engagement with the cam surface 286 on shaft 203. The left pin 485 in its rearmost position locks the mold jaw 403, the rear wall plate 411 and the side wall 503 of the galley 420 together, whereby the locked parts are held stationary during the mold setting and plunger changing operations. The right pin 486 serves to lock the mold jaw 404, the rear mold plate 412 and the galley head 500 together for causing the locked parts to move as a unit against the action of spring 414, then drawn to the right by lever 495 acting on the L-shaped projection 496 attached to mold jaw 404. Said lever 495 is pivoted to the machine frame at 497 (Fig. 16) and has a roller 498 arranged to engage a suitable groove in cam 287 on shaft 203.

While the tapered pins 485 and 486 are being operated to lock the parts as above described, the stepped slide 402 is being moved at its initial position over to the extreme right by means of long lever 499 (Fig. 12) carrying the lever bar 1449 on which is mounted the pin 1451 arranged to engage one of slots 437 of the stepped slide 402, said lever 1449 being in all respects similar to the lever 449 excepting that a flat spring 1450 (Fig. 11) replaces the tension spring 451. Said spring 1450 has a suitable indentation 1452 for tending to maintain the rear end of said lever 1449 in whatever position it happens to be in. The slide actuating lever 499 is slidably mounted near its front end on a block 1453 suitably pivoted in the standard 1454. One end of a bent lever 1455 (Fig. 12) engages the front end of said lever 499 at 1456, the other end of said bent lever carrying a roller 1457 engaging a suitable groove 289 in cam 288, on shaft 203, an arm 1458 extending from standard 1454 serves to pivotally support said lever 1454 at 1459.

It will be understood that the throw of the stepped slide actuating lever 499 is always constant due to the action of cam 288. However, in moving the stepped slide 402 to its initial position from whatever set of steps on said slide which happens to be in operation at the time, it will be seen that the

amount of the movement of said slide necessary to bring it to its initial position must necessarily vary depending on which set of steps is in operation. It will also be recalled that the bell crank lever 446 is operated to give the stepped slide a movement limited entirely within one set of steps. To avoid interference between the lever 446 due to its constant swing, the slide 402 due to the variable length of the movement thereof to its initial position, and the limited movement of said slide 402 in casting type of a given point size, I provide means which automatically disconnects bell crank lever 446 from said slide, when lever 499 is thrown into engagement therewith, and I provide additional means for disconnecting lever 499 from said slide when said slide has reached its initial position whereby part of the movement of the lever 499 to the right is not communicated to said slide.

When the size of type is to be changed and shaft 203 begins the first half of its revolution, the lever 1459 (Fig. 12) pivoted on standard 1454 at 1460, and carrying a roller 1461 engaging cam 290 on shaft 203, is rotated about said pivot the rearmost end of said lever engaging the foremost end of lever 449, whereby said last mentioned lever is rotated against the action of spring 451 to withdraw pin 451 from that slide notch 437 in which it happens to be. This rotation of lever 1459 at the same time raises the left end of the forked lever 1462, (Fig. 11) which is pivoted at 1463 on a suitable bracket extending from bearing 448, and which engages the front end of lever 1449, so that the pin 1451 is raised sufficiently to enter that notch 437 immediately to the right of the one from which pin 451 has just been withdrawn. The flat spring 1450, past the indented portion of which the rear end of said lever 449 has been forced, serves to hold said lever in its slide engaging position, until said lever is released by means soon to be described. Cam 288 now begins to impart motion to lever 449 to cause said lever to move the stepped slide toward its initial position, which position is at the point where the right end of lever 1464, pivoted at 1465 on bracket 440, engages the shoulder 1402 near the right end of said slide, said lever riding up on the inclined face 1401 of said slide against the action of the compression spring 1466. The lever 1464 is thereby lifted about its pivot 1465 carrying with it the link 1467 attached at its upper end at 1468 to said lever, and attached at its lower end to a forwardly extending lever 1469 pivoted on the extension 1470 of bracket 440 at 1471. (Fig. 13.) Said lever 1469 carries an arm 1472 extending to the left a sufficient distance to engage the under forward end of lever 1449 during its motion toward the right, and is lifted together with said arm 1472.

1472 through link 1467 when the lever 1464 rides up on the surface 1401 as above described. Since the arm 1472 is raised just as the shoulder 1402 of the slide 402 reaches its initial position in contact with the right end of lever 1464, the arm 1472 becomes operative through the connections above described, to withdraw the pin 1451 from the notch 437 against the action of the flat spring 1450 which then tends to maintain said pin in its disengaged position.

Referring to Fig. 16, we may now continue the description of the positions assumed by the mold parts during the type size change operation. At this time, the plunger 401 is in the position last described in contact with the front vertical face of the mold plate 411 while the stepped slide 402 is being moved over to its initial position as above described. It will be recalled that the pins 485 and 488 are pushed forward by the U-shaped arm 491 when the type size change is about to be made. Simultaneously the tapered pin 464 is withdrawn from the plunger 401 by the cam plate 1473 secured to the U-shaped lever 491, on the rearward movement of said lever, against the action of spring 465. Cam 287 now operates to actuate lever 495 to move jaw 404, rear mold plate 412, and galley head 500 toward the right, through the L-shaped projection 496.

The plunger sections 459 to 463 inclusive being unsupported in any manner will then drop down guided by the walls of openings 472 and 473 on to the blocks 469 and bracket 405, tapered pins 470 entering the tapered holes 471, the horizontally disposed pins 474 having been withdrawn out of the way by arm 477 acting against the heads 1478 of said pins when the clamp yoke 476 has been first released, said pins 474 being held out of the way until the type size change has been completed.

The mold and its allied parts having reached the positions above described on the first half of the revolution of shaft 203, all of the sub-mechanisms of the machine are halted in their operations until the proper matrix block has been selected. Thereafter, the second half revolution of shaft 203 effects the resetting of the mold for the new size of type and brings all of the operating parts back to their normal positions.

When properly energized through a suitable perforation in the strip 60, certain of the magnets 479 operate corresponding rods 468 to lift the blocks 469, and therethrough certain plunger sections, into operative position. Shaft 203 now causes cam 287 to release projection 496 through lever 495 whereby the springs 414 cause mold jaw 404, rear mold plate 412 and the galley head 500 to move toward the left until the operative plunger sections are clamped between the mold jaws 403 and 404. Immediately there-

after, arm 477 is swung to the right, causing the rounded end 481 of the clamp yoke 476 to lock the rear mold plates 411 and 412 together, the space 413 being thereby made exactly equal to the plunger thickness. Simultaneously the heads 1478 of the spring pressed pins 474 are released by the arm 477, whereby said pins are allowed to re-enter the tapered holes in the inoperative plunger sections for firmly holding said sections in place. (Fig. 18.) Pins 485 and 486 may now be withdrawn from the mold jaws by the forward movement of the U-shaped arm 491, urged thereto by the springs 487 and 488, tapered pin 464 being urged to re-enter the tapered hole in the plunger sections by spring 465 on the forward movement of cam plate 1473.

The substitution of the new plunger sections having been thus completed, the stepped slide 402 may now be allowed to move from its initial position at the extreme right towards the left under the influence of the flat spring 441 until halted in its path by the proper one of the stops 445 thrown up by one of the magnets 1480 in the usual manner, for the selection of that set of stops governing the face width of type of the desired point size. It is advisable to relieve the pressure of the plunger on the rear face of the flange 439 of slide 402, due to the spring 433, before said slide moves to the left, by means of the bent arm 1481 carried in slotted guide 1482 and operated by cam 291 on shaft 203 through roller 1483, said arm acting against the front plunger plate 1484 to move said plunger rearwardly out of engagement with the stepped slide.

Before said slide 402 can be moved to the left from its initial position it becomes necessary to raise lever 1464 out of engagement with the shoulder 1402 of said slide. This is accomplished through the cam 292 on shaft 203 engaging the roller 1485 on the lever 1486, pivoted at 1487 on a suitable lug 1488 projecting from standard 1454, and connected at its right end to an L-shaped lever 1489 pivoted at 1490, said lever 1489 being secured at its upper end to the forwardly extending lever 1469. Said cam 292 on the second half of the revolution of shaft 203 through the connection described, lowers the upright portion of bent lever 1489, thereby rotating lever 1469 about its pivot 1471 to raise the link 1467 and therethrough raising the lever 1464 out of engagement with the shoulder 1402.

The stepped slide operating lever 499 is brought back to its normal position by its cam 288, on the second half of the revolution of shaft 203, the cam 290 acting at this time to lower the lever 1459, thereby allowing pin 451 to enter one of the notches 437, and allowing the left end of forked lever 130

1462 to drop whereby the right end of said lever is positioned to allow the front end of lever 1449 to enter said fork on the completion of the movement of lever 499 to its 5 normal position. It will be understood that when the stepped slide is moved towards the left from its initial position, the compression spring 1466 brings lever 1464 to its normal position, and that the cam 291 withdraws arm 1481 to allow spring 433 to draw the plunger forward to its normal position.

To summarize the movements of the mold parts on the first half of the revolution of shaft 203, the jaws and plunger are first brought into the position assumed thereby after a line has been pushed into the galley, the clamp yoke 476 is loosened and the pins 474 withdrawn, the pins 485, and 486 pushed 20 forward the tapered pin 464 removed from the plunger, the jaw 404 moved toward the right, the pin 451 being withdrawn from the stepped slide, and pin 1451 substituted therefor, said slide being moved toward the 25 right and locked in its initial position, and all the plunger sections but section 458 dropped on to blocks 469. The plunger sections needed for the new size of type are then raised into operative position, the projection 496 released to close the mold jaw on the operative plunger sections, the yoke clamp 476 locked and the pins 474 inserted to hold the inoperative plunger sections, the 30 tapered pin 464 inserted into the operative plunger sections, the locking pins 485 and 486 being withdrawn at the same time, the plunger pushed back out of engagement with the stepped slide, the stepped slide unlocked from its initial position and brought to the 35 left against a step set selecting stop, pin 451 allowed to enter a notch 437, and all the remaining parts brought back to their normal positions.

The galley, the galley head, and the operating mechanism therefor.—Referring to Figs. 3, 14, 16, and 24, a galley 420, of the usual type, provided with an adjustable rear wall 502, front wall 503, and a galley head 500, and the usual type controlled devices 50 and clamps, which need not here be detailed, is arranged to receive the type. It will be seen that the galley head 500 in order to move a line of type into the galley must be given a stroke from right to left. However 55 to forward type lines of various point sizes, it becomes necessary to vary the stroke of said galley head each time a new point size of type is cast.

The means for attaining this result comprises a bell crank lever 504 having one arm 510 thereof arranged to engage the pin 506 on the underside of the galley head, a slot 505 being cut in said lever into which said pin enters. A slid able block 507 arranged for reciprocation in the groove 508

of the machine frame carries the adjustable pivot 509 of said bell crank lever. A second arm 511 has a downward projecting extension 512, said extension 512 carrying a pin 513 arranged in the slot 514 of the link 515, said link being pivoted at one end on the pin 516, extending downwardly through the long arm 517, which arm reaches across the rear part of the machine. It will be remembered that on changing the point size 70 of type, the arm 477 unlocks the yoke clamp 476 and the mold jaw pin 486 is pushed through the mold jaw 404, the rear mold plate 412, and into the tapered hole 518 of the galley head 500. 80

The movement of arm 477 is communicated to the bell crank lever 519 pivoted to the frame of the machine at 520 and there-through to a second yoke clamp 521 which is pivoted at 522 to the upstanding pin 516, 85 whereby the link 515 is unlocked from the long arm 517. Consequently, when the jaw 404 and the parts locked therewith are moved towards the right to their initial positions, the galley 500 communicates its motion through the pin 506 to the bell crank lever 504, the pin 513 moving freely in the slot 514 of the link 515, said link being allowed by said yoke clamp 521 to swing freely about its pivot 516. Immediately thereafter 90 the sliding arm 522 mounted in a suitable guide 523 is thrown rearwardly by means of a suitable cam 293 on shaft 203 to push the pivot carrying slide 507 into its initial position, on the second half of the revolution of 100 shaft 203. The proper one of stops 524 may now be thrown up by the proper one of magnets 525 which are controlled from the strip 60 in the usual manner. For positioning the pivot 509 so that the bell crank lever gives 105 the galley head 500 the proper stroke, a spring 526 draws the slide 507 forwardly up to the stop 524. On the release of the projection 496 by the lever 495, the mold jaw 404 and the galley head 500 locked thereto 110 are brought to the left, whereby said parts are adjusted to the new size of type, the bell crank lever being rotated about its pivot during the aforesaid motion, pin 513 of arm 512 positioning itself in slot 514 of the link 115 515. The arm 477 on its return to its normal position rotates the bell crank lever 519, whereby the yoke clamp 521 is rotated about its pivot 522, and the link 515 locked to the long arm 517, so that the link 515 and the 120 arm 511 of the bell crank lever 504 are locked to form a rigid connection, movement of the long arm 517 causing said bell crank lever, to rotate about its pivot for imparting a stroke of the proper length to the galley 125 head, whereby the line of type is forwarded into the galley.

The pump and its operating mechanism.—

In a machine of this character in which type bodies containing widely different amounts 130

of metal must be cast, it becomes advisable to adjust the stroke of the pump supplying said metal in accordance with the size of the characters to be cast. I therefore limit the 5 stroke of the pump piston operating lever 601 (Figs. 5 and 7) mounted on shaft 602 which is carried by the bracket 603 upstanding from the frame of the machine. The crank arm 604 is mounted at its upper end 10 on the shaft 602, the lower end thereof being connected to the link 605, operated by cam 110 (Fig. 2) on shaft 102. The lower end of the said crank 604 is pushed toward the left by said cam to give the pump piston 606 15 its upward stroke in the inner pump cylinder 607, a suitable spring 608 then drawing said crank arm 604 toward the right when permitted to do so by said cam until said crank arm engages a stepped slide 609 (Fig. 3) 20 mounted in a suitable guide 610 on the machine frame for giving said pump piston its downward or metal feeding stroke. A bell crank lever 610' pivoted to the machine frame at 621 is arranged to connect the 25 stepped slides 602 and 609 operatively, the steps of said slide 609 being suitably designed to allow the crank arm 604 to move the proper distance under the influence of spring 608 to cause the piston 606 to feed 30 the proper amount of metal for the character involved, it being obvious that the act of selecting the proper step on the slide 402 can be utilized to select the corresponding step on slide 609.

35 To insure the feeding of metal only after the matrix and the mold parts are ready to receive said metal, a magnet 611 (Fig. 7) is energized in the usual manner by the return wires on the working circuit as will be 40 more fully described hereinafter. (Fig. 30.) A lever 612 (Fig. 7) pivoted at 613 carries one member 614 of the pump locking device, the other member 615 of the said device being carried on the lower end of crank arm 45 604, suitable teeth being formed on said members 614 and 615 to cause said members to become locked normally by the action of spring 616. Metal can be fed by the piston 606 only when the magnet 611 is energized 50 to unlock the members 614 and 615.

Referring to the container 617 for the molten metal, the pipe 418 is suitably connected to said container, the passageway 618 leading from the pump cylinder 607 to said 55 pipe. A check valve 619 of the usual type closes said passageway on the up stroke of the piston 606, at which time metal is admitted into the upper part of said cylinder from the container 617 by the opening of a suitable check valve as 620. The pipe nipple 419 is positioned under the mold space 400 in the usual manner to supply metal to said space, and has the up and down motion usually given to feed nipples of this charac-

ter, in conjunction with the up and down movement of the mold itself.

The justifier.—The justification system is similar to that used in previous machines of this type wherein the space quads are designed on the unit principle, and the justifier 70 is set to cast such quads under the control of the perforated strip, the holes in said strip having been made to set the justifier in accordance with a justification table of the usual type. In the aforesaid type of justification mechanism, the space quads in any line differ by no more than one unit, the proper number of space quads of one size being cast first, and then the proper number of space quads of the next size being cast 80 as indicated by the justification table computed in advance.

Previous justifier mechanisms have been designed for reciprocating motion of the contact arms, whereas I provide a rotary 85 disc branch board, the contact arms being kept stationary during the justification. This arrangement greatly simplifies the mechanisms necessary for justification and at the same time allows the casting of a line 90 limited in length only by the galley and galley mechanism.

Referring to Figs. 3, 35, 39 and 40, the mechanical movements of the justifier mechanisms are imparted thereto by the various 95 magnets, as will be shortly pointed out, and by the long arm 517 operated only at the end of a line, after the clutch member 1105 has been shifted to set the end of the line mechanism in position (Fig. 39), it being 100 understood that the justifier parts are set in advance of the casting of the line by means of suitable perforations in the strip 60.

The upstanding portion 527 (Fig. 40) of the long arm 517, in its movement towards 105 the right given thereto by the end of the line cam 162, engages the roller 700 supported by the bell crank levers 701 pivoted at 702 and secured to the slide blocks 703 mounted in the brackets 704 on the machine 110 frame. The contact arms 705 and 706 are each secured to one of said blocks 703 and are bent for suitable contact with the rotary disc 707 mounted on shaft 708. It will be seen that when long arm 517 reaches its 115 extreme position to the right, the crank lever 701 move the blocks 703 to their initial positions against the action of springs 708, said springs serving to draw said blocks back to the desired positions of said contact blocks 120 against the proper one of stop 708 thrown up in the path of said blocks by the selected magnet 709, said spring operating only after the long-arm 517 has been moved towards the left to release said crank levers 701.

The disc 707 comprises a series of alternate insulating sections 710, and conducting sections 711, said insulating sections being

joined to one main insulating piece 712 occupying a semi-circular portion of said disc and extending half way through the thickness of said disc, the conducting sections 711 having suitable grooves 713 cut in the underside thereof into which the conducting pins 714 connected to wires 715 enter. A wheel 716 on shaft 708 has a flat coiled spring 717 wound thereon, the end of said spring being connected to the upstanding flange 527 of arm 517, said shaft 708 carrying in addition the ratchet wheel 718 on the underside of which is mounted a roller 719 secured to said wheel by a screw 720. In its position to the extreme right, the long arm 517 tensions the spring 717 thereby rotating shaft 708, and unwinding spring 717 from wheel 716 to provide a sufficient amount of slack in said spring to cast a line of the greatest length desired when said long arm 517 moves back to its extreme left position.

To position said disc 707 in relation to said contact arms 705 and 706 for casting the proper number of space quads in the line, one of the stops 721 actuated by the proper magnet 722 is thrown up into the path of the roller 719 during the rotation of shaft 708 due to the tendency of spring 717 to rewind on wheel 716. It is obvious that a torsion spring of the usual type, not shown, may be mounted on the shaft 708 to assist spring 717 to rotate said shaft.

During the above described rotation of said shaft 708 it becomes necessary to disengage the pawl 723 pivoted at 724 from the ratchet wheel 718. The pawl trip magnet 725 actuates the arm 726 to throw the lug 727 of the pawl 723 over a sufficient distance to disengage the teeth of said pawl from said ratchet wheel, thereby allowing said ratchet wheel to rotate freely under the influence of the flat coiled spring 717, until halted (Fig. 39).

Contact arms 705 and 706 are positioned 180 degrees apart so that when one contact arm is on the upper surface of one of the narrow semi-circular conducting sections 711, the other arm is in contact with the wide semi-circular insulating sector 712. Each of the wires 715 lead to one of the stepped slide stop operating magnets for determining the width of a character or space, said width differing by one unit only in adjacent conducting sections 711. The stops 708 are so operated that one contact arm as 706 is always in contact with the next consecutive conducting section nearer the center of disc 707 than that conducting section with which the other contact arm as 705 is in contact.

The stops 721 are so operated that the number of space quads of a given size cast while one of the contact arms is on a conducting section, is determined thereby, after which the next consecutive conducting sec-

tion comes in contact with the other contact arm under the control of the escapement soon to be described for casting space quads differing in width by no more than one unit from the space quads previously cast. The escapement comprises the pawl 723 operated through the magnet 728 and bell crank lever 729 pivoted at 730, the upper end of said lever acting in the slot 731 of said pawl to rock the said pawl an amount sufficient to cause first one and then the other of said teeth to engage said ratchet wheel (Fig. 36) whereby said wheel is given a constant intermittent rotation causing disc 707 to move under the contact arms 705, and 706, under the influence of spring 717. A tension spring 732 serves to bring the bell crank lever 720 back to its normal position to complete the rocking motion of said pawl.

It will be seen from the above that since stop 721 is withdrawn out of the way of roller 719 after it has performed its function of setting the disc 707 to cast the proper number of space quads of a given unit, ratchet wheel 718 may have an indefinitely continued intermittent motion limited only by the amount of slack provided in the spring 717 by the motion of long arm 517 to the left, thereby enabling my improved machine to cast a line containing practically any number of space quads.

The wiring and magnets.—Reference to Figs. 29 and 30 will make clear the wiring arrangement to the various magnets, it being understood that there are three distinct electric systems or circuits; namely, the working circuit indicated by the full lines of Fig. 29 for controlling those parts operated through the shafts 100 and 102, the movements of which parts must be repeated for the casting of each character; the setting or justifying circuit indicated by the dotted line of Fig. 29 for controlling the setting of the justifier to determine the number of space quads and the size of said quads in any line. An additional needle having a device connection controls the end of the line clutch and the cam connected thereto, which in turn operates the means for giving the plunger a stroke long enough to eject the last character of a line from the mold clear of the galley front wall, and the means for moving the galley head to forward a line of type; and the type size changing circuit shown in Fig. 30 for controlling those parts operated by shafts 200 and 203, which parts must be adjusted when a new type is to be cast.

In the working circuit, attention need only be called to the fact that the wiring is arranged to prevent any operation of the metal pump unless the circuit is first closed to the various mold adjusting parts, the matrix selecting control, and the stepped slide control, the justifier escapement be-

ing energized when contact is made at the index head, no wires running therefrom to the switch. The electric current therefore, must first pass through the magnet controlling the above mentioned mechanism before it can pass through the magnet for operating the pump trip.

In the justifying circuit, it will be seen that the end of the line clutch must first be tripped through a contact formed on the working circuit before the switch member 80 can be moved over to close the said setting circuit.

In the type size changing circuit, an additional needle is provided in the index head for energizing the magnet to throw the clutch and to operate the switch for closing said circuit. The wiring is so arranged that after the clutch has been thrown to operate the shaft 203, the magnet controlling the pin which holds the right end of the base 360 of the centering arm holder 350 in place, is first dropped to allow said holder to be withdrawn. Fig. 30 will make clear the relative time in which the various magnets are energized to allow the mechanisms to operate in the proper succession, as heretofore set forth and as indicated by the perforations in the sample piece of the strip 60 shown in Fig. 34, it being that the perforations for controlling the resetting of the type size change mechanism to their initial positions on the second half revolution of shaft 203 should immediately follow the perforations controlling the shifting of clutch member 211.

Line cancel perforations are provided in said strip 60 in advance of the perforations for the characters in a line for throwing the clutch member 101 into neutral position thereby allowing the strip to be fed without any other of the mechanism operating to cast any characters until said clutch member 101 is again thrown into operative position.

From Figs. 24 and 28, the positioning of the magnet groups will be clear. The main magnet carrying plate 91 is rotatable about the pin 90 in lower bed plate 750, the wires leading to the magnets being provided with sufficient slack to allow plate 91 to be rotated to bring any one of the magnet groups to the front of the machine for repair, replacement or adjustment. A suitable tapered plug 92, engaging a corresponding tapered hole in the bed plate 50 insures the correct positioning of the magnets when they are brought back to their operative positions. Separable plates 92, on which each group of magnets is mounted, are so shaped that any one of said plates may readily be removed from plate 91 together with the magnet group thereon after the magnet wires have been first disconnected.

While I have described the preferred form of my invention, it will be apparent that numerous variations and changes therein

may be made within the scope of my invention as set forth in the following claims. Furthermore, while I have described the illustrated machine with considerable particularity, I have purposely omitted numerous details which can readily be supplied by one skilled in the art, particularly in relation to the portion of the machine whose operation is analogous to that of well-known machines in general use.

I claim—

1. In a type casting and setting machine, means for carrying a plurality of matrix blocks bearing fonts of different point sizes, and means for automatically shifting any one of said blocks into type casting position in engagement with the carrying means.

2. In an adjustable mold for having type of different point sizes cast therein, a pair of separable jaws and a plunger variable in thickness between said jaws.

3. In a type casting and setting machine, the combination with a type composing machine, of means for feeding a perforated strip directly from said composing machine to said casting machine for casting type in the same order as the composition is made.

4. In a type casting and setting machine, rotatable means for justifying a line of type comprising a rotatable disc having alternating sections of insulating and of conducting material, a pair of arms each contacting respectively with an insulating and with a conducting section, means for determining the face size of a quad and means electrically connecting said contact arms with said quad size determining means.

5. In a type casting and setting machine, a rotatable justifier comprising a disc having alternating sections of insulating and of conducting material, a pair of arms each one of said arms contacting respectively with an insulating and with a conducting section, and means for giving said disc a step by step motion.

6. In a type casting and setting machine, control means, a galley head, means for shifting said head to forward lines of type into the galley, and means operated directly from the control means for varying the amplitude of the shift according to the point size of the type.

7. In a type casting and setting machine, a holder for carrying a plurality of matrices, a mold, means for centering a matrix above said mold, and means for horizontally reciprocating said centering means for withdrawing said centering means from said holder on changing from one matrix block to another.

8. In a type casting and setting machine, a hinged frame located above a mold, a matrix block holder carrying a plurality of matrix blocks supported on said frame, and means for raising said frame about the

- hinged end thereof on changing from one matrix block to another.
9. In a type casting and setting machine, a rotatable holder for carrying a plurality of 5 matrix blocks, each carrying a font of type, means for rotating said holder for changing the operating matrix block, and means for operating a block to cast type therefrom while connected to the holder.
10. In a type casting and setting machine, a pump for feeding molten metal, and means for adjusting the stroke of said pump for casting type of substantially different point sizes.
11. In a type casting and setting machine, a series of magnet groups, and a plate pivoted near the center thereof on which said magnet groups are mounted for allowing any of said magnet groups to be brought to 20 the front of the machine.
12. The combination with a type casting and setting machine of a composing machine hingedly mounted to the frame of said casting machine for being folded out of the 25 way when not in use.
13. In a type casting and setting machine, a working circuit, a setting circuit, a type size controlling circuit, and an automatically operated switch for closing one of said circuits at a time.
14. In a type casting and setting machine, means for casting different point sizes of type comprising a mold, a reciprocating plunger in said mold, and a slide having a 35 series of steps thereon for each point size of type for limiting the reciprocatory movement of said plunger.
15. In a type casting and setting machine, means for casting type of different point 40 sizes, means for automatically selecting the size to be cast, and means for rendering said casting means inoperative while said selecting mechanism is operating.
16. In a type casting and setting machine, means for casting type of different face sizes 45 and for casting type of different point sizes, means for automatically controlling the sizes of type and the characters to be cast, and means for maintaining the controlling means 50 in any desired position for repeatedly casting the same character.
17. In a type casting and setting machine, means for casting type of different point sizes, comprising a rotatable holder for carrying a plurality of matrix blocks located 55 above a mold, means for rotating said holder for changing the matrix block and an adjusting mold, and means for halting the 60 operation of the remainder of said machine during the operation of said holder rotating means.
18. In a type casting and setting machine, a mold, a reciprocating plunger in said mold, a slide having a series of stops 65 thereon for each point size of type for
- limiting the reciprocatory movement of said plunger, means for lowering the said mold and plunger with respect to said slide, and means for ejecting a cast type from said mold.
19. In a type casting and setting machine, a matrix block holder carrying a plurality of matrix blocks, each carrying a type font means for rotating said holder for selecting the required matrix block, and 70 means for centrally supporting said holder during the rotation thereof shiftable relative to the holder.
20. In a type casting and setting machine, means for intermittently feeding a 80 perforated magnet-controlling strip intermittently operated means for establishing control connections through said strip, and means for manually disengaging said feeding means for causing said machine to cast 85 the same character repeatedly without interrupting the intermittent operation of said connection-establishing means.
21. In a type casting and setting machine, means for casting type of different 90 point sizes, means for automatically selecting the size of type to be cast, means for justifying a line of any size type, and means for forwarding a line of any size of type bodily.
22. A holder for carrying a plurality of matrix blocks comprising a pair of polygonal end members, a series of connecting members having edge grooves wherein said matrix blocks are slidably mounted, and 95 means for shifting a block in said groove into registration with a mold.
23. In an adjustable mold wherein type of different point sizes may be cast, a sectional plunger, and enlarged ends on the 100 sections of said plunger arranged to nest one adjacent to the other.
24. In a type casting and setting machine, an adjustable mold comprising a pair of 105 separable jaws and a sectional plunger arranged between said jaws, and means for varying the thickness of said plunger between said walls for changing the point size of type to be cast in said mold.
25. In a type casting and setting machine, 110 a justifier adapted to cast any number of space quads in a line comprising a rotatable disc, insulating material in one half of said disc, alternate sections of insulating and of conducting material in the other half of said 115 disc, means for rotating said disc, magnet controlled stops for halting said disc at any desired point in its rotation a pair of arms each contacting respectively with an insulating and with a conducting section, means 120 for determining the face size of a space quad and means electrically connecting said contact arms with said quad size determining means, a ratchet wheel operatively connected to said ratchet wheel to move intermit- 125

- tently through a predetermined angle at a time.
26. In a type casting and setting machine, a galley head, and means for giving said galley head a variable stroke, comprising a pivoted lever operatively connected to said galley head, means for operating said lever, and magnet controlled means for shifting the pivot of said lever.
- 10 27. In a type casting and setting machine, a vertically reciprocating matrix centering arm, a horizontally slidably arm for carrying said centering arm, a slide for said slidably arm, and means for accurately positioning said slidably arm.
- 15 28. In a type casting and setting machine, a frame pivoted at one end thereof, a rotatable matrix block holder carried by said frame, and a pair of vertically reciprocating pins for raising one end of said frame when said holder is to be rotated.
- 20 29. In a type casting and setting machine, a rotatable holder for carrying a plurality of matrix blocks, a ratchet wheel coaxially secured to said holder, a pawl for rotating said ratchet wheel when one matrix block is to be substituted for another, and means for operating said pawl until the substitution is completed.
- 25 30. In a type casting and setting machine, a mold adjustable for casting different point sizes of type, a mold plunger means for adjusting said plunger in said mold, a pump for supplying molten metal to said mold, and means for adjusting the stroke of said pump operatively connected to said plunger adjusting means.
- 30 31. In a type casting and setting machine, means for casting type of different point sizes, a main shaft, means on said main shaft for actuating said type casting means, means for automatically selecting the size of type to be cast and for automatically adjusting said casting means to the type size, a second shaft arranged at an angle to said main shaft and means on said second shaft for actuating said type size selecting means.
- 35 32. In a type casting and setting machine, a main shaft, means operatively connected to said main shaft for casting type of different point sizes, a second shaft arranged substantially at right angles to said main shaft, means for automatically selecting the size of type to be cast and for automatically adjusting said casting means to the type size, operatively connected to said second shaft, and a clutch for automatically disconnecting said casting actuating means while the type size selecting means is operating.
- 40 33. In a type casting and setting machine, a rotatable matrix block holder, a hub on said holder and a movable stud arranged to enter said hub for supporting said holder during the rotation thereof and to withdraw from said hub after the rotation of said holder has been completed.
- 45 34. In a type casting and setting machine, a rotatable matrix block holder having a series of centering holes in the ends thereof, a pivoted frame carrying said holder, pins 70 for engaging some of said holes for keeping said holder down on said frame and for accurately positioning said holder on said frame, and means for causing said pins to release said holder during the rotation of 75 said holder.
- 50 35. In a type casting and setting machine, means for casting type of different point sizes and means for automatically selecting the size of type to be cast comprising a rotatable holder for carrying a plurality of matrix blocks each carrying a type font, and means for shifting a predetermined block into casting position while in the holder, including means for rotating said holder, 80 and means for halting the rotation of said holder when the desired matrix block reaches casting position.
- 55 36. The combination with a type casting and setting machine of a composing machine 90 hingedly mounted to the frame of said casting machine for being folded out of the way when not in use, and means for feeding a perforated strip from said composing machine to said casting machine for casting 95 type in the same order as the composition is made.
- 60 37. In a type casting and setting machine, means for carrying a plurality of matrix blocks each carrying a type font, means for 100 automatically selecting any one of said matrices for casting type in cooperation therewith, and line justifying means.
- 65 38. In a type casting and setting machine, means for casting type of different point 105 sizes, means for automatically selecting the size of type to be cast magnet controlled line justifying means, and magnet controlled line forwarding means.
- 70 39. In a type casting and setting machine, means for carrying a plurality of matrix blocks each adapted for casting a different size of type, means for automatically selecting any one of said matrix blocks, and an adjustable mold for cooperation with the 110 selected block for having type of different point sizes cast therein.
- 75 40. In a type casting and setting machine, means for carrying a plurality of matrix blocks each adapted for casting a different 120 size of type, means for automatically selecting any one of said matrix blocks, an adjustable mold having a pair of separable jaws and a plunger variable in thickness arranged between said jaws, said mold cooperating with the selected matrix block for casting type of the desired size.
- 80 41. In a type casting and setting machine,

- means for carrying a plurality of matrix blocks each adapted for casting type of different point sizes, means for automatically selecting any one of said matrix blocks, 5 an adjustable mold for cooperation with the selected block for having type of different point sizes cast therein, justifying means, and automatically adjustable means for forwarding a cast line of type into a galley.
- 10 42. In a type casting and setting machine, means for casting type of different point sizes, means for automatically selecting the size of type to be cast, and a rotary justifier adapted to be set automatically for controlling the size of the space quads to justify a line of type.
- 15 43. In an adjustable mold wherein type of different point sizes may be cast, a plunger for determining the point size of type to be cast in said mold comprising a series of adjacent sections, certain of said sections being removable from said plunger to vary the thickness thereof, the total thickness of all the sections being equal to the point size of 20 the largest type to be cast, the thickness of the individual sections being determined by the difference in successive point sizes of type to be cast.
- 25 44. In an adjustable mold wherein different point sizes of type may be cast, a plunger for determining the point size of type to be cast comprising a series of relatively movable sections, means for holding each of the operative sections in intimate contact with the adjacent operative sections, means for removing sections not required when a change is to be made to a point size of type smaller than that being cast, and means for adding sections required when a change is 30 to be made to a point size of type larger than that being cast.
- 35 45. In an adjustable mold wherein different point sizes of type may be cast, a rear mold wall comprising a pair of lapped separable plates, side walls comprising a pair of separable jaws, a front wall comprising a sectional plunger, means for moving said jaws and said plunger for ejecting a type between said rear wall plates, and means for 40 adjusting the mold for a new point size of type comprising means for operatively connecting each of the rear wall plates with the jaw adjacent thereto, while the type size change is being made, means for separating said jaws whereby the plunger sections are 45 allowed to drop from between said jaws, means for raising the plunger sections required for spacing said jaws to cast the point size of type desired, and means for 50 drawing said jaws together for clamping said jaws against said plunger.
- 55 46. In a type casting and setting machine, means for casting type of different point sizes, a galley, a galley head, means for 60 changing the stroke of said galley head on
- changing the size of type to be cast for allowing the line of type of the new size to be forwarded into said galley comprising a pivoted lever operatively connected to said galley head, a second lever connected to said pivoted lever, means for setting and clamping said second lever in adjusted position, a series of stops for determining the position of the pivot of said pivoted lever, and means for operating said second lever after 65 a line has been cast.
- 70 47. In a type casting and setting machine, means for casting type of different point sizes, a holder for carrying a plurality of matrix blocks, a mold, a vertically reciprocating arm for centering a selected matrix above said mold operating normally in said holder, and means for removing said centering arm from said holder when the size of type is to be changed comprising a horizontally slidable arm carrying said centering arm, a slide on which said slidable arm is mounted, a pair of pin stops for accurately positioning said slidable arm in said holder, and means for lowering said stop 80 when said slidable arm is operated.
- 85 48. In a type casting and setting machine, means for casting type of different point sizes, a frame pivoted at one end thereof, a holder for carrying a plurality of matrix blocks carried by said frame, means for rotating said holder for selecting any one of said matrix blocks, and vertically reciprocating pins for raising one end of said frame when said holder is to be rotated.
- 90 49. In a type casting and setting machine, means for casting type of different point sizes, a rotatable holder for carrying a plurality of matrix blocks, means for rotating said holder when a matrix block other than 95 that in operation is to be selected, and a clutch for automatically disconnecting the remaining type size changing and adjusting mechanism during the rotation of said holder.
- 100 50. In a type casting and setting machine, means for casting type of different point sizes, comprising an adjustable mold, a reciprocating plunger for determining the point and face size of the type body to be cast, means for adjusting the thickness of said plunger, a slide having a series of steps thereon for each point size of type for limiting the reciprocatory movement of said plunger, a pump for supplying molten metal 115 to said mold and a second slide having a series of steps thereon for each point size of type operatively connected to said first mentioned slide for limiting the stroke of said pump.
- 110 51. In a type casting and setting machine, means for casting type of different point sizes comprising an adjustable mold, a reciprocating mold plunger for determining the point and face size of type body to be 120 cast, and a pump for supplying molten metal to said mold.
- 125 65

cast, means for adjusting the thickness of said plunger, means for limiting the reciprocatory movement of said plunger, means for carrying a plurality of matrix blocks, 5 means for selecting the matrix to cooperate with said mold for casting a type, and means for adjusting said limiting means when the point size is changed.

52. In a type casting and setting machine, 10 means for casting type of different point sizes, an electric circuit for controlling said casting means, justifier setting means, an electric circuit for controlling said setting means, means for changing the size of type 15 to be cast, an electric circuit for controlling said type size changing mechanism, a clutch operative to disconnect said casting means when the size of type is to be changed, and a switch for closing one of said circuits at a 20 time.

53. In a type casting and setting machine, means for casting different point sizes of type comprising an adjustable mold, a reciprocating sectional plunger in said mold, a slide 25 having a series of steps thereon for each point size of type for limiting the reciprocatory movement of said plunger, means for moving said slide to select the desired series of steps when the size of type is to be 30 changed, and means for moving said slide for selecting the face size of the desired character.

54. In a type casting and setting machine, an adjustable mold for having type of different 35 point sizes cast therein, a reciprocating sectional plunger operating in said mold for determining, the point size of a type, a stepped slide for cooperation with said plunger for determining the face size of a type, 40 means for lowering said mold and plunger with respect to said slide, and means for ejecting a cast type from said mold.

55. In a type casting and setting machine, means for casting type of different point 45 sizes, comprising a holder for carrying a plurality of matrix blocks, means for selecting any one of said blocks, an adjustable mold cooperating with said matrix blocks for casting a type, and means for forcing a 50 current of air through said mold for cooling said mold.

56. In a type casting and setting machine, means for casting type of different point sizes comprising a holder for carrying a plurality of matrix blocks means for automatically selecting any one of said matrix blocks, an adjustable mold for cooperating with the selected block for casting a type, a reciprocating sectional plunger in said mold for 60 determining the point size of the type, means cooperating with said plunger for determining the face size of a type, means for forcing an air current through said mold for cooling said mold, and means for justifying a line 65 of type.

57. In a type casting and setting machine, an adjustable mold wherein type of different point sizes may be cast, a reciprocating sectional plunger serving as the rear wall of said mold for determining the point and 70 face size of the type, means for limiting the reciprocation of said plunger, means for decreasing the thickness of said plunger, means for increasing the thickness of said plunger, and means for forcing air through said mold 75 for cooling said mold.

58. In a type casting and setting machine, means for casting type of different point sizes, means for selecting the size of type to be cast, comprising a holder for carrying 80 a plurality of matrix blocks and means for rotating said holder for bringing one of said blocks in to casting position, a clutch for disengaging said casting means when the size of type is to be changed, means for 85 holding said clutch in position wherein the casting means is disengaged while said type size selecting means is operating comprising a magnet controlled clutch member engaging fork, and a magnet controlled spring-pressed pin, a clutch for disengaging the 90 remainder of said type size changing mechanism during the rotation of said matrix block holder, and means for holding said last mentioned clutch in disengaging position 95 comprising a second magnet-controlled clutch engaging fork, and a second magnet controlled spring pressed pin.

59. In a type casting and setting machine, an adjustable mold, wherein type of different 100 sizes may be cast, a pair of separable plates forming the rear wall of said mold, means for relatively adjusting said plates, and means for temporarily locking said plates in the adjusted position comprising 105 a forked clamping lever and means for operating said lever when the size of type is to be changed.

60. In a type casting and setting machine, a holder for carrying a plurality of matrix 110 blocks comprising a pair of polygonal end members and a series of connecting members having edge grooves in which said matrix blocks are slidably mounted, an adjustable mold for cooperation with any one of said 115 matrix blocks for casting type, and means for automatically rotating said holder for selecting the required matrix block.

61. In a type casting and setting machine, a holder for carrying a plurality of matrix 120 blocks comprising a pair of polygonal end members and a series of connecting members having edge grooves in which said matrix blocks are slidably mounted, means for rotating said holder for selecting any one 125 of said matrix blocks, an adjustable mold for cooperation with a matrix block for casting type comprising a pair of separable jaws and a sectional plunger arranged between said jaws, and means for varying the thick- 130

ness of said plunger for changing the point size of type to be cast in said mold.

62. In a type casting and setting machine, means for casting type of different point sizes, means for automatically selecting the size of type to be cast, and a rotary justifier adapted to allow the casting of number of space quads in a line comprising a rotatable disc, insulating material in one half of said disc, alternate sections of insulating and of conducting material in the other half of said disc, means for rotating said disc, stops for halting said disc at any desired point in its rotation, a pair of arms contacting respectively with the insulating half and with a conducting section, means for determining the face size of a quad space, and means electrically connecting said contact arms with said quad size determining means, and 20 an escapement for permitting said disc to move intermittently.

63. In a type casting and setting machine, means for casting type of different point sizes, means for automatically selecting the size of type to be cast, means for justifying a line of type comprising a rotatable disc, part of the upper half of said disc being made of insulating material, alternate sections of insulating and of conducting material in the other part of said disc, a pair of arms contacting respectively with an insulating half with a conducting section, an escapement for allowing said disc to move intermittently and means operatively connecting said conducting sections with quad space size determining means, a galley head, and means for giving said galley head a variable stroke comprising a pivoted lever operatively connected to said galley head, 40 means for operating said lever, and means for adjusting the pivot of said lever.

64. In a type casting and setting machine, means for casting type of different point sizes, a holder for carrying a plurality of matrix blocks comprising a pair of polygonal end members and a series of connecting members having edge grooves in which said matrix blocks are slidably mounted, an adjustable mold for cooperation with any one 50 of said matrix blocks for casting type, means for forcing air through said mold for cooling said mold, means for rotating said holder for selecting the required matrix block, justifying means, and means for forming a line of type.

65. In a type casting and setting machine, a rotatable holder for carrying a plurality of matrix blocks comprising a pair of polygonal end members and a series of connecting members having edge grooves in which said matrix blocks are mounted, a ratchet wheel coaxially secured to said holder, a pawl for rotating said ratchet wheel when one matrix block is to be substituted for another, means for operating said pawl until

the substitution is completed, and an adjustable mold for cooperation with any one of said matrix blocks for casting type.

66. In a type casting and setting machine, a frame pivoted at one end thereof, a rotatable holder for carrying a plurality of matrix blocks carried by said frame, a ratchet wheel coaxially secured to said holder, a pawl for rotating said ratchet wheel when one matrix block is to be substituted for another, means for operating said pawl until the substitution is completed, and vertically reciprocating pins for raising one end of said frame when said holder is to be rotated.

67. In a type casting and setting machine, means for casting type of different point sizes, means for selecting the size of type to be cast, including a rotatable matrix holder, a clutch for rendering said casting means inoperative when the size of type is to be changed, means for locking said clutch during the type size changing operation and for releasing said clutch at the completion of said operation, a second clutch for rendering inoperative the remainder of the type size selecting mechanism during the rotation of said matrix holder, means for locking said second clutch during the rotation of said holder and means for releasing said clutch at the completion of said rotation.

68. In a type casting and setting machine, a frame pivoted at one end thereof, a rotatable holder for carrying a plurality of matrix blocks carried by said frame, comprising a pair of end members and a series of connecting members having edge grooves wherein said matrix blocks are slidably mounted, ratchet wheels secured to said end members, pawls for rotating said ratchet wheels when one matrix block is to be substituted for another, and pins for raising one end of said frame when said holder is to be rotated.

69. In a type casting and setting machine, means for casting type of different point sizes, means for selecting the size of type to be cast including a rotatable matrix holder, a main shaft, means on said main shaft for actuating said type casting means, a clutch on said main shaft for rendering said casting means inoperative when the size of type is to be changed, means for automatically selecting the size of type to be cast and for automatically adjusting said casting means to the type size, a second shaft arranged substantially at right angles to said main shaft, means on said second shaft for actuating said type size selecting means, and a clutch on said second shaft for rendering inoperative the remainder of the type size selecting mechanism during the rotation of said matrix holder.

70. In a type casting and setting machine, a holder for carrying a plurality of matrix blocks comprising end members and a series

of connecting members having edge grooves wherein said matrix blocks are slidably mounted, means for selecting the block from which the type is to be cast, means for justifying a line of type and means for forwarding a line of type bodily.

71. In a type casting and setting machine, means for carrying a plurality of matrix blocks, an adjustable mold for cooperation with any one of said matrix blocks for casting type, means for selecting a matrix, a plunger operating in said mold, means for adjusting the thickness and position of said plunger in said mold prior to the casting operation, a pump for supplying molten metal to said mold, means for adjusting the stroke of said pump, means for justifying a line of type, and means for forwarding a line of type bodily.

72. In a type casting and setting machine, a holder for carrying a plurality of matrix blocks comprising end members and a series of connecting members having edge grooves wherein said matrix blocks are slidably mounted, an adjustable mold comprising a pair of separable jaws and a sectional plunger arranged between said jaws, means for adjusting the thickness of said plunger, a slide for adjusting the plunger in said mold, a pump for supplying molten metal to said mold, means operatively connected to said plunger, adjusting slide for adjusting the stroke of said pump, a galley head, and means for giving said galley head a variable stroke for forwarding lines of type of different sizes.

73. In a type casting and setting machine, a frame pivoted at one end thereof, a rotatable matrix block holder carried by said frame, a pair of pins for raising one end of said frame when said holder is to be rotated, a matrix centering arm, a slidable arm for carrying said centering arm, means for accurately positioning said slidable arm in the matrix centering position, an adjustable mold comprising a pair of separable jaws and a sectional plunger arranged between said jaws, means for forcing air through said mold for cooling said mold, means for adjusting the thickness of said plunger and a stepped slide for adjusting the plunger in said mold.

74. In a type casting and setting machine, a frame pivoted at one end thereof, a rotatable matrix holder carried by said frame, a pair of pins for raising one end of said frame when said holder is to be rotated, means for rotating said holder when the size of type is to be changed, a matrix centering arm, a slidable arm carrying said centering arm, means for accurately positioning said slidable arm in the matrix centering position, a mold adjustable for having type of different sizes cast therein, a sectional plunger forming the front wall of said mold,

automatically adjusted means for supplying molten metal to said mold, a rotary justifier, and a variable stroke galley head.

75. In a type casting and setting machine, a rotatable matrix block holder having a series of centering holes in the ends thereof, a pivoted frame carrying said holder, pins for engaging some of said holes for accurately positioning said holder on said frame, means for causing said pins to release said holder during the rotation of said holder, a hub on said holder, a movable stud arranged to enter said hub for supporting said holder during the rotation thereof and to withdraw from said hub after the rotation of said holder has been completed.

76. In a type casting and setting machine, a rotatable matrix block holder comprising end members and a series of connecting members having edge grooves wherein said matrix blocks are slidably mounted, means for rotating said holder, said holder having a series of centering holes in the ends thereof, a frame carrying said holder, pins for engaging some of said holes for positioning said holder on said frame, means for causing said pins to release said holder during the rotation of said holder, a movable stud arranged to support said holder during the rotation thereof and to be disengaged from said holder after the rotation of said holder has been completed.

77. In a type casting and setting machine, a rotatable matrix block holder comprising end members having centering holes therein, and a series of connecting members, a frame carrying said holder, means for entering said centering holes for positioning said holder on said frame, and for withdrawing from said holes during the rotation of said holder, a movable stud arranged to support said holder during the rotation thereof and to release said holder after the rotation of said holder has been completed, pins for raising one end of said frame during the rotation of said holder, an adjustable mold in which type of different point sizes may be cast, a sectional plunger operating in said mold means for varying the thickness of said plunger and adjustable means for supplying molten metal to said mold.

78. In a type casting and setting machine, a matrix block holder comprising end members and a series of connecting members in which said blocks are slidably mounted, means for selecting any one of said matrices, an adjustable mold wherein type of different point sizes may be cast in cooperation with said selected matrix, a mold plunger, a slide for adjusting said plunger in said mold for determining the face size of the type, a pump for supplying molten metal to said mold, and means operatively connected to said slide for adjusting the stroke of said pump.

79. In an adjustable mold wherein type of different point sizes may be cast, a reciprocating plunger forming the front wall of the casting space, a slide having a series of 5 steps for each size of type for limiting the frontward reciprocation of said plunger for determining the face size of the type to be cast, and having a series of slots in the under side thereof, and means for shifting 10 said slide when a change is to be made in the point size of type comprising a cam operated lever, a short lever carried by said cam operated lever, a pin adapted to enter said slide slots carried near one extremity of said 15 short lever, and means for causing said pin to engage said slide.
80. In combination with an adjustable mold wherein type of different point sizes may be cast, a reciprocating plunger forming the front wall of the casting space, a slide having a series of steps for each point size of type for limiting the frontward reciprocation of said plunger for determining the face size of the type to be cast, and 20 having a series of slots on the under side thereof, means for shifting said slide when a change is to be made in the point size of type and means for selecting one of the 25 steps of a series comprising a bell crank lever, a short lever carried by said bell crank lever, a pin adapted normally to enter a slide slot mounted on said short lever near the extremity thereof, and means for withdrawing said pin from said slot when 30 the point size of type is to be changed.
81. In a type casting and setting machine, a galley head for forwarding a line of type operable only after a full line has been cast, and means for operating said galley head 35 comprising a bell crank lever, pivoted at one end, a slotted lever, said bell crank lever having one arm connected to said galley head and having another arm loosely connected to said slotted lever, means for adjusting said galley 40 head for setting said slotted lever, means for clamping said slotted lever in the set position, a slide on which said bell crank lever is pivoted, and a series of stops for adjusting said slide to shift the pivot of 45 50 said bell crank lever for determining the stroke of said galley head.
82. In an adjustable mold wherein type of different point sizes may be cast, a rear mold wall comprising a pair of lapped separable plates, side walls comprising a pair of separable jaws, and a front wall comprising a sectional plunger, a galley head, means for moving said jaws relatively to said plates to type ejecting position, a pin 55 for temporarily connecting one of said plates with the adjacent jaw when the point size of type is to be changed, a second pin for temporarily connecting the other plate, the jaw adjacent thereto and the 60 galley head, and means for further separating said jaws for adjusting the thickness of said plunger and for setting the galley head operating mechanism.
83. In an adjustable mold wherein type of different point sizes may be cast, a sectional plunger forming the front wall of said mold, a pin for maintaining the plunger sections in operative position during the casting of type of the same point size, means for withdrawing said pin when the size of type is to be changed, spring pressed pins for maintaining the plunger sections not required in inoperative position, and means for withdrawing said last mentioned pins when the size of type is to be changed.
84. In a type casting and setting machine, a clutch designed to be tripped after a complete line has been cast, a link operatively connected to said clutch, rotary justifier mechanism including a pair of contact arms, a slide for each of said arms, magnet controlled stops in the path of said slide, and a bell crank lever operatively connecting said slide and said link for setting said contact arms to justify the succeeding line.
85. In a rotary justifier mechanism, a contact disc, a ratchet wheel arranged coaxially with said disc, a pawl cooperating with said ratchet wheel, means for bringing said disc to its initial position when the casting of a line is to be begun, and a magnet for operating said pawl for allowing said wheel and disc to move step by step during the casting of a line.
86. In a rotary justifier, a disc of insulating material, and sections of conducting material each having a part equal to substantially half the circumference and half the depth thereof removed and having a groove in the under side thereof, said sections being inserted in said disc at spaced intervals.
87. In a type casting and setting machine, means for casting type of different point sizes, comprising a mold, a holder for carrying a plurality of matrix blocks, means for selecting the size of type to be cast comprising means for rotating said holder and means for halting the rotation of said holder when the desired matrix block reaches casting position, means for centering a matrix above said mold and means for withdrawing said centering means from said holder when the holder is to be rotated.
88. In a type casting and setting machine, means for casting type of different point sizes comprising an adjustable mold, a pump for feeding molten metal to said mold, means for adjusting the stroke of said pump, and a holder for carrying a plurality of matrix blocks means for rotating said holder, means for halting the rotation of said holder when the desired matrix block reaches the casting position, means for cen-

tering a matrix above said mold, and means for withdrawing said centering means when said holder is to be rotated.

89. In a type casting and setting machine, 5 means for casting type of different point sizes, a holder for carrying a plurality of matrix blocks, means for rotating said holder, means for halting the rotation of said holder when the desired matrix block reaches casting position, means for controlling 10 the sizes of type and the characters to be cast, and means for maintaining the controlling means in any desired position for repeatedly casting the same characters.
90. In a type casting and setting machine, 15 means for casting type of different point sizes, a holder for carrying a plurality of matrix blocks, means for rotating said holder, means for halting the rotation of said holder when the desired matrix block reaches casting position, a mold, a reciprocating plunger in said mold, a slide having 20 a series of steps thereon for each point size of type for limiting the frontward reciprocation of said plunger, means for lowering said mold and plunger with respect to said slide, and means for ejecting a cast type from said mold in the lowered position of said mold.
91. In a type casting and setting machine, 25 means for casting type of different point sizes comprising an adjustable mold, a reciprocating plunger in said mold, a slide, having a series of steps thereon for each point size of type for limiting the frontward reciprocation of said plunger, means for lowering said mold and plunger with respect to said slide, means for ejecting a cast type from said mold in the lowered position 30 of said mold, a pump for feeding molten metal to said mold, means for adjusting the stroke of said pump, and a holder for carrying a plurality of matrix blocks, and means for rotating said holder.
92. In a type casting and setting machine, 35 means for casting type of different point sizes comprising an adjustable mold, a holder for carrying a plurality of matrix blocks, means for selecting the size of type to be cast comprising means for rotating said holder, means for centrally supporting said holder during the rotation thereof, and means for halting the rotation of said holder when the desired matrix block reaches casting position, means for centering a 40 matrix above said mold, and means for withdrawing said centering means from said holder when the holder is about to be rotated.
93. In a type casting and setting machine, 45 means for casting type of different point sizes comprising a rotatable holder for carrying a plurality of matrix blocks, means for rotating said holder for selecting the required matrix block, means for centrally 50 supporting said holder during the rotation thereof, and an adjustable mold, a magnet controlled rotary justifier, and variable stroke line forwarding means.
94. In a type casting and setting machine, 55 means for casting type of different point sizes comprising a rotatable holder for carrying a plurality of matrix blocks, a pivoted frame on which said holder is slidably mounted, means for raising said frame during the rotation of said holder, means for supporting said holder from and accurately positioning said holder with respect to said frame, when said holder is not being rotated, means for rotating said holder, means for centrally supporting said holder during the rotation thereof, and an adjustable mold, a rotary justifier, and variable stroke line forwarding means.
95. In a type casting and setting machine, 60 means for casting type of different point sizes, comprising a holder for carrying a plurality of matrix blocks, means for rotating said holder for selecting the desired matrix block an adjustable mold for cooperation with the selected matrix block for casting type, an adjustable plunger operating in said mold, a main shaft, means on said main shaft for actuating the adjusted mold plunger and the selected matrix for 65 causing said mold and matrix to cast and eject type of the same point size, a second shaft arranged substantially at right angles to said main shaft, and means on said second shaft for adjusting said mold and plunger and for rotating said holder.
96. In a type casting and setting machine, 70 a holder for carrying a plurality of matrix blocks, an adjustable mold wherein different point sizes of type may be cast, means for rotating said holder for selecting one of said matrix blocks, an arm for centering a selected matrix above said mold operating normally in said holder, means for removing said centering arm from said holder when the size of type is to be changed, a rear mold wall comprising a pair of separable plates, side walls in said mold comprising a pair of separable jaws, a front wall in said mold comprising a sectional plunger, 75 means for moving said jaws and said plunger for ejecting a type between said rear wall plates, and means for adjusting said mold for a new point size of type.
97. In a type casting and setting machine, 80 a holder for carrying a plurality of matrix blocks, an adjustable mold wherein different point sizes of type may be cast, means for rotating said holder for selecting one of said matrix blocks, an arm for centering a selected matrix above said mold, operating normally in said holder, means for removing said centering arm from said holder when the size of type is to be changed, a rear mold wall comprising a pair of sepa- 85

rable plates, mold side walls comprising a pair of separable jaws, a mold front wall comprising a sectional plunger, means for moving said jaws and said plunger for ejecting a type between said rear wall plates, means for a galley head, and means for changing the stroke of said galley head on changing the size of type to be cast for al-

lowing the line of type of the new size to be forwarded into said galley.
